VARIABLE SPEED GOVERNING MECHANISM
WITH MODIFIER

Meyer-Frenkel, London, England

Application March 30, 1950, Serial No. 152,846
In Great Britain June 20, 1949

20 Claims. (Cl. 264—3)

1 The present application is a continuation-in-part application of the application Serial No. 111,841, filed August 22, 1949, now abandoned.

This invention relates to variable speed governing mechanism comprising a speed responsive device (e. g. a centrifugal mechanism) and an adjustable resilient balancing mechanism therefore, where said balancing mechanism includes a lever transmission arrangement between a spring means and a sleeve of said speed responsive device, which is adapted to have motion responsive to changes of speed of rotation. The general theory underlying this invention is given in the paper entitled "Formulation of stability-equations" and derivation of new constructions, with complex systems of design-formulae, for variable speed control mechanisms," published in the Proceedings of the "Institution of Mechanical Engineers," London, 1953.

This invention also relates to variable speed governing mechanisms comprising means for adjusting the frictional resistances.

The performance of a variable speed governor is determined by three main influences, viz. the effect of the speed responsive device (such as a centrifugal mechanism), the effect of the resilient balancing mechanism (such as a spring-lever balancing mechanism) and the effect of resistances opposing governing motion, i. e. the resistance of the control-organ of the apparatus to be governed, together with all other frictional resistances.

The fundamental differences between these influences are:

Consider first a governor with a spring-lever balancing mechanism; the moment of this resilient balancing mechanism at the fulcrum of its lever depends on two mutually independent variables, viz. firstly, on the adjustment of the balancing mechanism for the mid-position of the lever, denoted by the distance $BC = x$ between the fulcrum B of the lever and the point of action C thereon of the balancing spring, with reference to a system of co-ordinates having its origin fixed to the fulcrum B, each value of x in the mid-position of the lever having a corresponding speed-setting; and secondly on the position of the sleeve-member of the speed responsive device, which said lever engages, denoted by its distance z from its mid-position (as analysed exactly later). Therefore this moment is denoted by $S(x, z)$, being the moment of the spring-lever balancing mechanism at its fulcrum, at an adjustment of the spring-lever mechanism denoted by x , the distance of the point of action C of the spring

2 on the lever from the fulcrum B of the lever in the mid-position thereof—which characterises the speed-setting—and for the sleeve-position at distance z from the mid-position thereof, where 5 z can be positive or negative. Accordingly, at one and the same sleeve-position at a certain speed-setting, corresponding to certain values of x and z , the moment of the balancing mechanism can have only one value, viz. $S(x, z)$.

10 In contrast to this, the moment of the speed responsive device at the fulcrum of the lever, which is a function of the spindle-speed ω , and will hence be denoted by L_ω , may at one and the same sleeve-position have different values, of 15 which only one, corresponding to a certain value of the spindle-speed, can be equal to the balancing moment $S(x, z)$, at the same sleeve-position in the static state. This is because there are altogether three influences acting, viz. the moment 20 of the resilient balancing mechanism, the moment of the centrifugal mechanism, and the moment of the frictional- and control-organ-resistance, of which in a state of static equilibrium the moment of the friction- and control-organ-resistance may, at the same sleeve-position, have 25 different values, including zero.

In the static state, at which the moment of the friction- and control-organ-resistance is zero, i. e. these are not in action, the moment L_ω of the centrifugal mechanism must equal the moment $S(x, z)$ of the balancing mechanism at the sleeve-position and speed-setting in question, where to this value of moment L_ω corresponds a certain value of the spindle-speed.

35 When now the spindle-speed changes from this certain value at the same sleeve-position, the moment L_ω of the centrifugal mechanism (being function of ω) changes, while the moment $S(x, z)$ remains the same at the same sleeve-position at 40 the same speed-setting, and the resulting difference in the moments calls into action the moment of the control-organ of the engine being governed, and of frictional resistance, to maintain 45 static equilibrium. With progressive change in the spindle-speed, the difference between the moments of the centrifugal mechanism and the balancing mechanism grows until a state is reached in which motion of the sleeve is about to start, i. e. when the difference in the moments L_ω and $S(x, z)$ equals the moment of the limiting values of the control-organ resistance and of the friction.

50 Thus, in the state when the friction- and control-organ resistances are not in action and there

is equilibrium at a certain sleeve-position and speed-setting between only the balancing moment $S_{(x,z)}$ and a certain value of the moment L of the centrifugal mechanism, to which corresponds a certain value of the spindle-speed ω , this value of the spindle-speed must, just like moment $S_{(x,z)}$ be dependent on the variables x and z , and one can therefore denote it by $\omega_{(x,z)}$ and the corresponding value of the moment of the centrifugal mechanism by $L_{\omega(x,z)}$ where corresponding to $S_{(x,z)}$, the suffix x denotes the dimension characterising the adjustment of the spring-lever balancing mechanism in the mid-position of the sleeve, and the suffix z the ordinate of the sleeve-position in the system of coordinates having its origin at the mid-position of the sleeve.

This state is the "beginning" of static equilibrium with regard to z and x , and can also be called "equilibrium at the beginning of a steady state" for a certain sleeve-position in a certain speed-setting, the spindle-speed corresponding to it being $\omega_{(x,z)}$ and its equation of equilibrium generally

$$L_{\omega(x,z)} = S_{(x,z)} \quad (1)$$

and for the mid-position of the sleeve, where $z=0$

$$L_{\omega(x,0)} = S_{(x,0)} \quad (2)$$

where $\omega_{(x,z)}$ is the spindle-speed corresponding to the mid-position in that speed-setting, in short, the speed-setting.

However, for the spindle-speed changing from a value $\omega_{(x,z)}$ for beginning of static equilibrium, the change of moment of the centrifugal mechanism will at first not go to change the sleeve-position z , but will first bring into action the moment of the control-organ and friction resistance, so that accordingly, this change of moment of the centrifugal mechanism will have nothing to do with changes in x and z , but corresponding to a change of spindle-speed $\Delta\omega$ bringing the moment to a value

$$L_{(\omega(x,z)+\Delta\omega)}$$

will be

$$\left(\frac{\partial L_{\omega(x,z)}}{\partial \omega}\right)_z \Delta\omega = L_{(\omega(x,z)+\Delta\omega)} - L_{\omega(x,z)} = F \quad (3)$$

where F is the moment of the friction and control-organ resistance called into action.

If one denotes by $\Delta_F\omega$ the change in spindle speed from $\omega_{(x,z)}$, which brings about a change from the "beginning" of static equilibrium to a state when motion (of the sleeve, lever, etc.) is about to start, i. e. when the change in moment of the centrifugal mechanism

$$\frac{\partial L_{\omega(x,z)}}{\partial \omega} \Delta_F\omega$$

equals the moment F_x of the limiting values of the friction and control-organ resistance, according to

$$\left(\frac{\partial L_{\omega(x,z)}}{\partial \omega}\right)_z \Delta_F\omega = L_{(\omega(x,z)+\Delta_F\omega)} - L_{\omega(x,z)} = F_x \quad (4)$$

the state brought about by this change is the "end" of static equilibrium in relation to x and z , also denoted by "equilibrium at the end of a steady state."

The equation of the "end" of static equilibrium is hence

$$L_{(\omega(x,z)+\Delta_F\omega)} = S_{(x,z)} \pm F_x \quad (5)$$

Now, in order to determine the constructions

of resilient balancing mechanisms (e. g. spring-lever balancing mechanisms) in relation to the requirements for required performance of the governor at different speed-settings, one has to derive equations in which only the influence of the centrifugal mechanism and the influence of the resilient balancing mechanism are represented, while the influence of the control-organ resistance and of friction do not occur, and this has been done in the above-mentioned paper published by the Institution of Mechanical Engineers, London, 1953.

(1) It is the object of this invention to provide constructions of variable speed governing mechanisms, which can be adjusted to any speed-setting over a wide range with only one actuating motion and without obstructing governing, and which should govern stably for each speed-setting of this range. This requires that, at any one speed-setting, the governor should provide for any value of the shaft speed its corresponding position of the control-sleeve, at which the governor is at the "beginning" of static equilibrium, and vice versa, that for any one speed-setting, to each position of the control-sleeve should correspond its value of the shaft speed, at which the governor is at the "beginning" of static equilibrium, where the extreme values of such spindle-speeds correspond to the extreme positions of said control-sleeve, and thus to the extreme adjustments of the control-organ of the engine being governed, and where, as defined, the "speed-setting" denotes the shaft speed corresponding to the mid-position of the control-sleeve, at which the governor is at the "beginning" of static equilibrium.

(2) The governor should be sensitive at each speed-setting, for example, the governor should, for each sleeve position at any one speed-setting, begin governing action for the smallest change of the shaft speed from the value for the "beginning" of static equilibrium, limited only by the condition that the governor should not be sensitive to the unavoidable variations of shaft speed occurring in a state of constant mean shaft speed. Expressed mathematically, this means that twice the difference in shaft-speed $\Delta_F\omega$ from the "beginning" to the "end" of static equilibrium at any sleeve-position, expressed as fraction of the speed-setting

$$\frac{2\Delta_F\omega}{\omega(x,0)} = \epsilon_x$$

and denoted by the degree of insensitivity of governing, should be a minimum for each speed-setting, limited by the condition that it should not be smaller than ξ , the degree of speed-fluctuation of the rotating masses, which is twice the greatest deviation $\Delta_c\omega$ from the mean shaft speed which occurs at constant mean shaft speed, expressed as fraction of the speed-setting

$$\frac{2\Delta_c\omega}{\omega(x,0)} = \xi_x$$

Accordingly this object is to make $\epsilon_x \approx \xi_x$ for each speed-setting, in order to bring about governing at a predetermined smallest deviation from the mean shaft speed, but to prevent the governor being sensitive to the variations of shaft speed at constant mean shaft speed. For the degree of speed-fluctuation ξ_x of the rotating masses varying over the range of speed-settings, as e. g. in reciprocating engines, it is thus the object of the invention to provide constructions, in which, with the one adjusting motion for change of speed-

setting, the degree of insensitivity of governing is varied according to $\epsilon_x \approx \xi_x$ over the range of speed-settings. For example, in reciprocating engines, in which, as proved later, the degree of speed-fluctuation ξ_x of the rotating masses rises with the speed-setting being reduced, due to the influence of the reciprocating masses, it is thus the object to provide constructions which, with the one adjusting motion for a change of speed-setting increase the degree of insensitivity ϵ_x with falling speed-setting, and vice versa, according to $\epsilon_x \approx \xi_x$.

(3) At each speed-setting of the range, the difference between the extreme values $\omega_{x, \max}$ and $\omega_{x, \min}$ of the shaft speed, corresponding to the extreme positions of the control-sleeve, should be a required fraction of the speed-setting itself ($\omega_{(x, 0)}$ being the shaft speed corresponding to the "beginning" of static equilibrium in the mid-position of the sleeve),

$$\omega_{x, \max} - \omega_{x, \min} = \delta_x$$

$$\omega_{(x, 0)}$$

which is denoted as the degree of irregularity δ_x of the governor. Where this degree of irregularity δ_x of the governor should thus have a development over the range of speed-settings, which is in accordance with requirements. It is accordingly a further object of the invention to provide constructions supplying any required development of the degree of irregularity over the range of speed-settings, all with the one adjusting motion of the governing mechanism for a change of speed-setting.

(4) Since the performance of a governor together with the engine to be governed is characterised at any speed-setting by

$$\tau_x = \delta_x + \epsilon_x$$

the "total" degree of irregularity (also called percentage run-up) at that speed-setting, it is accordingly object of the invention to provide constructions of variable speed governing mechanism which, with maintenance of stability, effect a required development of the "total" degree of irregularity (percentage run-up) τ_x over the range of speed-settings, with only one actuating motion for a change of speed-setting.

The requirements for stability given under (1) necessitate that, at any one speed-setting,

(a) The governor should not, for one and the same position of the control-sleeve supply two different values of the shaft speed, at which the governor is in equilibrium at the "beginning" of static equilibrium, and

(b) That the governor should not provide, for different positions of the control-sleeve between the extreme positions thereof, the same value of the shaft speed at which the governor is at the "beginning" of static equilibrium.

This results in the conditions for stability that, for two adjacent positions of the sleeve, a distance dz apart, the respective values of the shaft speed for the "beginning" of static equilibrium must differ from one another according to

$$\frac{d\omega_{(x, z)}}{dz} > 0$$

and finite, z , the distance of the sleeve-position from the mid-position thereof, being measured positively in the direction which corresponds to an increase in the value of $\omega_{(x, z)}$, which conditions must be valid for a value of z between its extreme values $-\Delta a$ and $+\Delta a$.

Further, according to how exactly the gover-

nor provides static equilibrium at the "beginning" of the steady state for each sleeve-position between the extreme positions at any one speed-setting, the stability provided can be of different orders, of the 1st, 2nd, third order up to the n th order.

Thus, for stability of the 1st order, the speed-responsive device and the spring-lever balancing mechanism of the governor must be so constructed, that for any value of z , the ordinate of the control-sleeve-position, between the extreme values $-\Delta a$ and $+\Delta a$ thereof, the equilibrium equation

$$S_{(x, z)} - L_{\omega_{(x, z)}} = 0 \quad (1)$$

is valid only when one neglects the terms containing small quantities of the 2nd order

$$\text{(such as } \frac{\Delta a^2}{2!}, \dots \text{)}$$

20 in the series developments of $S_{(x, z)}$ and $L_{\omega_{(x, z)}}$ respectively in terms of their values $S_{(x, 0)}$ and $L_{\omega_{(x, 0)}}$ at the mid-position of the sleeve and of the derivatives thereof, for the case that

$$\frac{d}{dz}(S_{(x, 0)} - L_{\omega_{(x, 0)}}) = 0 \quad (25)$$

but that

$$\frac{d^2}{dz^2}(S_{(x, 0)} - L_{\omega_{(x, 0)}}) \neq 0$$

30 For stability of the second order, the spring lever balancing mechanism for a given speed responsive device must be constructed such that for any value of z , the distance of the control-sleeve from its mid-position, between the extreme values $-\Delta a$ and $+\Delta a$ thereof, the equilibrium equation

$$S_{(x, z)} - L_{\omega_{(x, z)}} = 0 \quad (1)$$

40 is valid only when one neglects the terms containing small quantities of the third order

$$\text{(such as } \frac{\Delta a^3}{3!}, \dots \text{)}$$

45 in the series developments of $S_{(x, z)}$ and $L_{\omega_{(x, z)}}$ in terms respectively of $S_{(x, 0)}$ and $L_{\omega_{(x, 0)}}$ and the derivatives thereof, for the case that the construction provides

$$\frac{d}{dz}(S_{(x, 0)} - L_{\omega_{(x, 0)}}) = 0 \quad (25)$$

and

$$\frac{d^2}{dz^2}(S_{(x, 0)} - L_{\omega_{(x, 0)}}) = 0 \quad (32)$$

55 but

$$\frac{d^3}{dz^3}(S_{(x, 0)} - L_{\omega_{(x, 0)}}) \neq 0$$

60 Corresponding considerations apply to stability of higher orders, up to any required n th order.

In accordance with the above considerations, it is object of this invention to provide constructions of governor in which the order of stability is high, and in particular, constructions of variable speed governing mechanism, in which the order of stability is high at each speed-setting of the range—in contrast to present constructions—and in which, with observance of the objects given before, the adjustment for a change of speed-setting takes place with one actuating motion only. Thus it is object of the invention to provide for given speed responsive devices, constructions of spring lever balancing mechanism which make the governor supply stability up to

the n th order, i. e. which bring the construction into accordance with the above differential equations of the first to the n th order; for each speed-setting of the range with only one adjusting motion for change of speed-setting.

It must be stated generally that as a minimum requirement a spring-lever balancing mechanism has to satisfy at least the stability-differential equations of the first order (25) and of the second order (32), because it will be understood from a series expression for the moment $S_{(x,z)}$ at any sleeve-position in terms of the moment $S_{(x,0)}$ at the mid-position and the derivatives thereof, that a governor merely satisfying the stability-equation of the first order can only be stable for a very small sleeve-travel about the mid-position of the sleeve, and that a governor must at least also satisfy the stability-equation of the second order in order to be stable over a normal sleeve travel, and that it should preferably satisfy higher orders of stability-equations as well.

Before stating the provisions of the present invention, for achievement of the above objects, let it first be considered in short, whether and how far known constructions of spring-lever balancing mechanism can supply stability over a range of speed-settings.

Consider a known type of spring-lever balancing mechanism, represented diagrammatically in Fig. 14, which comprises a lever DBC, fulcrumed on a fixture at B and having the sleeve of the centrifugal mechanism acting on it at D, and a balancing spring, say a tension spring, which is suspended (e. g. pin-jointed) at C to a block movable along the lever for a change of speed-setting, but fixed for the same speed-setting, and which spring is suspended at A^0 to an anchorage supported so as to be immovable also for change of speed-setting. For governing action at the same speed-setting, e. g. rocking of the lever about its fulcrum B with motion of sleeve D, the spring-means, suspended at points C and A^0 , rocks about these points. With distance CA^0 representing the total length of the spring between its points of suspension, the deflection l_x of the spring beyond its unstrained length U_0 , which deflection determines the force exerted by the spring, is represented by length CA, leaving the length AA^0 to represent the unstrained length U_0 of the spring.

With suspension as method of engagement between the spring and the lever, the moment of the balancing mechanism at its fulcrum

$$S_{(z,0)} = kl_x \cdot x \cdot \sin \phi = S_{(z,0)}(x, l_x, \phi)$$

where distance $BC=x$, and with k the rate of the spring, l_x its deflection and ϕ the angle between the centre-line of the spring and the lever in its mid-position.

The construction is characterised in that, for a change of speed-setting, the point of engagement C of the spring with the lever, which is immovable for governing at the same adjustment, is moved along the lever, rotating the spring about its point of anchorage A^0 , which remains fixed, and altering its total length A^0C . This motion thus adjusts: Firstly, the distance $BC=x$ between fulcrum B of the lever and the point of action C thereon of the spring, secondly, the angle ϕ between the centre-line of the spring and the lever in the mid-position, and thirdly, the deflection l_x of the spring beyond its unstrained length U_0 , this adjustment of the deflection being determined by the motion of point C along the straight lever and the motion of point

5 A, which represents the end of deflection l_x set off from C, in the arc of a circle with radius $AA^0=U_0$ about the fixed support-point A^0 , which circle represents the locus of points A for all adjustments.

10 For minimum stability, one has for each speed-setting the three equations given by the equilibrium Equation 2, the stability-equation of the first order (25) and the stability-condition of the second order (32). These three equations must be satisfied at each speed-setting, and since the moment $L_{\omega(x,0)}$ of the centrifugal mechanism and its derivatives are functions of the speed-setting $\omega_{(x,0)}$, the equations will require for each speed-setting different values of x , l_x and ϕ , the dimensions determining $S_{(x,0)}$, which the construction should provide.

Whereas, however, the construction provides a development of the deflection l_x with change of speed-setting, which is given by the motion of end-point C of the spring along the straight lever and the motion of point A, denoting the end of the deflection set off from C, in the arc of a circle of radius U about fixed point A^0 , the three equations would, in general, require a development of l_x which, for the same motion of point C along the lever, would make the point A move along some curve to suit the equations, and not a circle with radius U about A^0 .

20 Accordingly (as also proved exactly after the detailed description of the invention), such a spring-lever balancing mechanism cannot provide the minimum necessary order of stability over a range of speed-settings, due to the development of the deflection l_x being geometrically predetermined. To provide a displacement of point A along a required curve instead of along a circle about A^0 one would have to adjust distance $AA^0=U_0$, the unstrained length of the spring, which, however, would require a second adjustment motion in this construction, which is against the object, and also has other faults, as shown later, which make this inapplicable. Therefore, in order to vary the deflection l_x in accordance with the stability-equations, while keeping distance $AA^0=U_0$, the unstrained length of the spring, unchanged during change of speed-setting, one has to be able to displace the point of engagement A^0 of the spring anchorage with its support, which is immovable during governing at the same speed-setting, along a required path. This varies for a change of speed-setting also the distance BA^0 and angle β (see Fig. 14), which determine the position of engagement point A^0 , relative to fulcrum B and the lever, together with the other adjustments of the spring-lever balancing mechanism, and all this has to be done with one actuating motion.

More generally, as will be shown hereafter, 60 in order to provide the minimum order of stability, constructions have to be provided which, while displacing the point of engagement A^0 of the spring anchorage with its support in order to vary the spring-deflection l_x in accordance with the stability-equations, also vary, with the same adjusting motion, at least another three of the dimensions of the spring-lever balancing mechanism, viz: x , ϕ , A^0B , β , y , Δ_a , in accordance with the stability-equations, where Δ_a is the half sleeve-travel of the speed responsive device. Furthermore, a construction such as that diagrammatically represented in Fig. 14 requires its adjustment means to be connected to the lever DBC in order to be able to effect displacement 70 of the engagement-point C of the spring along

the lever during change of speed-setting, e. g. the block from which the spring is suspended may be moved along the lever by means of a screw mounted thereon and actuated through bevel-gearing mounted on fulcrum B.

The present invention provides for adjustment means for the spring-lever balancing mechanism, which is entirely out of contact with the lever, thus avoiding any frictional or other resistances to rocking of the lever due to such adjustment means either during governing action at the same speed-setting, or more particularly during change of speed-setting, which would obstruct the operation of the governor.

To achieve these objects, the present invention provides:

A variable speed governing mechanism which comprises a fixture; a governor shaft rotatably mounted on said fixture; a speed responsive device having a sleeve-member for performing motion responsive to changes of speed of rotation of said governor shaft, means for transmitting motion of said sleeve-member to a control-organ of an apparatus to be governed; and an adjustable spring-lever balancing mechanism for said speed responsive device, which comprises a lever transmission arrangement; a spring means; an anchorage for said spring means; a support for said anchorage in all positions of said anchorage; a first connection means engaging both another part of said spring means and said lever transmission arrangement; a support for said fulcrum; a second connection means engaging both said lever transmission arrangement and said sleeve-member of said speed responsive device; and a speed-setting adjustment means comprising a first means for displacing relative to said fixture at least one of three components respectively recited as said first connection means, said fulcrum and said second connection means; a second means for displacing said anchorage of said spring means relative to said support of said anchorage, relative to said fixture and relative to said first connection means with a change in the distance between said anchorage and said first connection means, said anchorage being immovable relative to said fixture with said displacement means in the same position; and one actuating means for said first and said second displacement means, the said actuating means being out of contact with said lever transmission arrangement; the said speed-setting adjustment means effecting the said displacements of the said components to involve a change in the deflection of said spring means at least for the mid-position of said sleeve-member, and the said displacements of the said components being mutually interdependent, being carried out simultaneously with only one actuating means and corresponding to one another.

In other words, the invention provides for a spring lever mechanism with means for effecting, during change of speed-setting, a change of transmission ratio of the lever (by one of several methods: e. g. displacement of the engagement point of the first engagement means from the spring means with the lever, displacement of the fulcrum, or displacement of the engagement point of the second engagement means from the sleeve-member with the lever, or any combination of such displacements) and simultaneously with this, due to the same adjusting motion, a change of the deflection of the spring means at least for the mid-position of the lever through displacement of said spring anchorage, which is

immovable relative to the fixture during governing at the same speed-setting, and relative to its support, relative to said fixture and relative to said first connection means.

Also according to the present invention, a variable speed governing mechanism which comprises a fixture, a governor shaft rotatably mounted on said fixture, a speed responsive device having a sleeve-member for performing motion responsive to change of speed of rotation of said governor shaft, and means for transmitting motion of said sleeve-member to a control-organ of an apparatus to be governed, has an adjustable spring-lever balancing mechanism which comprises: a lever transmission arrangement; a spring means; an anchorage for said spring means; a support for said anchorage in all positions of said anchorage; a first connection means engaging both another part of said spring means and said lever transmission arrangement; a fulcrum for said lever transmission arrangement; a support for said fulcrum; a second connection means engaging both said lever transmission arrangement and said sleeve-member of said speed responsive device; a means for limiting the travel of said sleeve-member of said speed responsive device; said limiting means comprising a stop; and speed-setting adjustment means comprising a first means for displacing relative to said fixture at least one of four components respectively recited as said first connection means, said fulcrum, said second connection means and said limiting means for the travel of said sleeve-member of said speed responsive device; a second means for displacing said anchorage of said spring means relative to said support for said anchorage, relative to said fixture and relative to said first connection means with a change in the distance between the said anchorage and the said first connection means, the said anchorage being immovable relative to said fixture with said speed-setting adjustment means being out of action; and one actuating means for said first and said second displacement means; the said actuating means being out of contact with said lever transmission arrangement; the said speed-setting adjustment means effecting the said displacements of the said components to involve a change in the deflection of said spring means at least for the mid-position of said sleeve-member; and the said displacements of the said components being mutually interdependent, being carried out simultaneously with only one actuating means, and corresponding to one another.

In other words, such an adjustable spring lever balancing mechanism may comprise means for effecting, at changes of speed-setting at least in the mid-position of said lever over at least a part of the range of speed-settings, guidance of the point of engagement A^0 between said spring anchorage and said support, which is immovable relative to said fixture during governing at the same speed-setting, along a path relative to a system of co-ordinates having its origin fixed to said fulcrum B of said lever, and one axis along the mid-position of said lever, and for effecting said guidance of said point of engagement A^0 during change of speed-setting with a change of the deflection l_x of said spring means, together with changes of at least another three of the predefined dimensions of the components of the spring-lever balancing mechanism $x, \theta, A^0B, \beta, y, \Delta a$, with only one actuating motion for said adjustment means. Said path of point A^0 relative to said system of co-ordinates having its ori-

11

gin at the fulcrum B of said lever and one axis along the mid-position of said lever, is determined by the dimensions x , θ and U_x for each speed-setting, in accordance with the equilibrium-equation

$$(S_{(z, 0)} - L_{\omega(z, 0)}) = 0 \quad (2)$$

and in accordance with at least the first stability differential equation of the series of stability differential equations from the first to the n th order:

$$\frac{d}{dz} (S_{(z, 0)} - L_{\omega(z, 0)}) = 0 \quad (25)$$

to

$$\frac{d^n}{dz^n} (S_{(z, 0)} - L_{\omega(z, 0)}) = 0 \quad (36)$$

where n is any positive integer including unity, $U_x = U_0 \pm l_x$ is the strained length of the spring means between the point of engagement A^0 of the anchorage with its support and the point of engagement C of its first connection means with said lever in its mid-position, where $L_{\omega(x, 0)}$ and $S_{(z, 0)}$ are the moments respectively exerted at the fulcrum B of said lever by the speed responsive device and by the spring lever balancing mechanism for static equilibrium between these two moments only, i. e. for the "beginning" of static equilibrium, in the mid-position of the sleeve, as defined before, and where z is the distance of said sleeve from the mid-position of said sleeve, measured positively in the direction of $\omega_{(x, z)}$ increasing, as hereinbefore defined.

Adjustable spring lever balancing mechanisms in accordance with this invention embody one of the following two methods of engagement of the balancing spring means with the lever:

(1) The method of engagement in accordance with the relation

$$\frac{dx}{d\beta} = x \cot \phi \quad (117)$$

(see appendix)

which requires that the point of engagement C of the first connection means from the spring means is movable during governing at the same speed-setting only in the direction of the line of action of the spring-means, which is maintained the same during governing at the same speed-setting, so that said first connection means has to be guided to be capable only of motion along

$$\frac{x}{l_x} = \sin \phi \left[\frac{y}{L_{\omega(x, 0)}} \left(\frac{\partial L_{\omega(x, 0)}}{\partial \omega} \frac{\partial \omega_{(z, 0)}}{\partial a} \frac{\partial \omega_{(z, 0)}}{\partial R} \frac{dR}{dz} \dots \right) - 2 \cot \phi \right] \quad (143)$$

said line of action of said spring, which is held stationary during governing at the same speed-setting, and engages the lever movably therewith (e. g. by means of a roller) during such governing.

(2) The second method of engagement in accordance with the relation

$$\frac{dx}{d\beta} = 0 \quad (119)$$

which requires that the point of engagement C of the first connection means from the spring means with the lever be fixed relative to the lever during governing at the same speed-setting, at least, e. g. the first connection means of the spring means with the lever provides for pin-jointing said spring means at a position on the lever, which is fixed during governing at the same speed-setting, whereby the line of action of said spring means rocks about its anchorage during governing at the same speed-setting.

12

(1) For the first method of engagement, of the spring means and lever, the equilibrium equation becomes

$$k \cdot x \cdot l_x \frac{1}{\sin \phi} - L_{\omega(x, 0)} = 0 \quad (129)$$

for any speed responsive device being used in the governor, $L_{\omega(x, 0)}$ being known therefore in terms of its properties and of $\omega_{(x, 0)}$.

(a) Generally, for any speed responsive device, the stability-equation of the first order becomes with such a spring-lever balancing mechanism

$$\frac{x}{l_x} = \frac{\sin \phi}{1} \left[\frac{1}{L_{\omega(x, 0)}} \left(\frac{dL_{\omega(x, 0)}}{dz} \right) \cdot y - 2 \cot \phi \right] \quad (128)$$

and the stability-equation of the second order

$$\frac{1}{L_{\omega(x, 0)}} \frac{d^2 L_{\omega(x, 0)}}{dz^2} = \frac{1}{y^2 \sin^2 \phi} \left[\left(\frac{x}{l_x} \right) 6 \cos \phi + 4 \cos^2 \phi + 2 \right] \quad (125)$$

and so on for higher orders of stability-equations. From these equations is determined the path, along which the adjustment means for the spring lever balancing mechanism displaces, during a change of speed-setting, the point of engagement A^0 between the spring anchorage and its support, said path being traced in the system of co-ordinates having its origin fixed to the fulcrum B of said lever and its X-axis along the mid-position of said lever, and said path being determined by the dimensions x , ϕ and U_x , which are obtained for each speed-setting from the above equilibrium and stability equations up the order required, where $U_x = U_0 \pm l_x$ for a tension or compression spring respectively. In Equations 128, 125, and so on, the derivatives of $L_{\omega(x, 0)}$ will be known for any speed responsive device, in terms of $\omega_{(x, 0)}$ and of the properties of the device, the expressions containing $\delta_{\omega(x, 0)}$ the degree of irregularity of the governor for the speed-settings.

(b) Still for any speed-responsive device, expressing the derivatives of $L_{\omega(x, 0)}$ in terms of the degree of irregularity $\delta_{\omega(x, 0)}$ and of the half sleeve-travel Δa (for the condition that

$$\frac{\partial \omega_{(z, 0)}}{\partial z}$$

the same for all sleeve-positions), the stability-equation of the first order becomes

where $M, R, \dots$ are dimensions of the speed-responsive device, for example, M the mass of centrifugal weights, R the mean radius of the path of such centrifugal weights, and so on and the stability-equations of the second and higher orders can be expressed in this form.

(c) Taking as an example of a speed responsive device a centrifugal mechanism with mass of rotating bodies M , mean radius of their path (corresponding to the mid-position of the sleeve) R , and transmission means between the centrifugal bodies and the sleeve providing for

$$\frac{dR}{dz} = U$$

and constant for all values of z , as is given by a ball and conical cup type centrifugal mechanism, for which half apex angle Θ of the cup the ratio

$$\frac{dR}{dz} = U = \tan \Theta$$

and to the force-ratio, the equilibrium equation becomes

$$k \cdot x \cdot l_z \cdot \frac{1}{\sin \phi} - \omega_{(z, 0)}^2 M \cdot R \cdot y = 0 \quad (54)$$

the stability-equation of the first order becomes

$$\frac{x}{l_z} = \left[\left(\frac{\delta \omega}{\Delta a} + \frac{U}{R} \right) y - 2 \cot \phi \right] \frac{\sin \phi}{1} \quad (144)$$

the stability-equation of the second order, in

$$\frac{x}{l_z} = \sin \phi \left[\frac{y}{L_{\omega(z, 0)}} \left(\frac{\partial L_{\omega(z, 0)}}{\partial \omega} \frac{\delta \omega}{\Delta a} \frac{\omega_{(z, 0)}}{2} + \frac{\partial L_{\omega(z, 0)}}{\partial R} \frac{dR}{dz} \right) + \cot \phi \frac{x \cot \phi \cos \phi}{U_0 \pm l_z} \right] \quad (158)$$

connection with 144, and due to $\delta \omega_{(z, 0)}$ having to be positive, provides

$$\frac{\delta \omega}{\Delta a} = - \frac{3 \cot \phi}{y} \frac{U}{R} \pm \sqrt{\left(\frac{U}{R} \right)^2 + \frac{3 \cot^2 \phi}{y^2} - \frac{2}{y^2}} \quad (155)$$

the stability-equation of the third order:

$$\frac{\delta \omega}{\Delta a} \left[\left(\frac{U}{R} \right)^2 - \frac{3}{\sin^2 \phi \cdot y^2} \right] = \frac{\left(\frac{U}{R} \right)^3 - 3 \cot \phi \left[\left(\frac{U}{R} \right)^2 - \frac{4}{y^2 \sin^2 \phi} \right]}{\Delta a \left[\left(\frac{U}{R} \right)^3 - 3 \cot \phi \right]} \quad (156)$$

the stability-equation of the fourth order:

$$\frac{\delta \omega}{\Delta a} \left[\left(\frac{U}{R} \right)^3 - 3 \cot \phi \right] = \frac{3}{\sin^2 \phi \cdot y^3} (3 - \sin^2 \phi) + \frac{3 \cos \phi \left(\frac{U}{R} \right)^3 - 3 \cot \phi \left[\left(\frac{U}{R} \right)^3 - \frac{3 \cos \phi}{y^3 \sin^3 \phi} \right]}{\Delta a \left[\left(\frac{U}{R} \right)^3 - 3 \cot \phi \right]} \quad (157)$$

From these equations, the path along which the adjustment means for the spring-lever balancing mechanism has to guide, during change of speed-setting, the engagement point A^0 between the spring anchorage and its support, relative to the system of co-ordinates, having its origin fixed to the fulcrum, B , of the lever and its X-axis along the mid-position of the sleeve, is determined from the dimensions x , ϕ and U , obtained for each speed-setting, from these equations, and as are also any other adjusted dimensions.

(2). For the second method of engagement between the spring means and the lever (e. g. pin-jointing to lever at position fixed thereon, during governing at the same speed-setting), the equilibrium-equation becomes

$$k \cdot x \cdot l_z \cdot \sin \phi - L_{\omega(z, 0)} = 0 \quad (141)$$

(a) Generally, for any speed-responsive device, the stability-equation of the first order becomes

$$\frac{x}{l_z} = \sin \phi \left[\frac{1}{L_{\omega(z, 0)}} \left(\frac{dL_{\omega(z, 0)}}{dz} \right) \omega_z y + \cot \phi \frac{x \cot \phi \cos \phi}{U \pm l_z} \right] \quad (142)$$

and the stability-equation of the second order can be obtained accordingly, and so on, for higher orders of stability equations. From these equations, in the same way as described for the other engagement means, is obtained the path, along which the adjustment means for the spring-lever balancing mechanism has to displace, for a change of speed-setting, the point of engagement A^0 of the spring anchorage with its support, relative to the system of co-ordinates defined above,

with its origin at the fulcrum B of the lever, and its X-axis along the mid-position of the lever.

(b) Expressing the derivatives of $L_{\omega(z, 0)}$ in terms of the degree of irregularity $\delta \omega_{(z, 0)}$ and of the half sleeve-travel (for the condition that

$$\frac{\partial \omega_{(z, 0)}}{\partial z}$$

is the same for all sleeve-positions), the stability-equation of the first order becomes

$$15 \quad \frac{x}{l_z} = \sin \phi \left[\frac{y}{L_{\omega(z, 0)}} \left(\frac{\partial L_{\omega(z, 0)}}{\partial \omega} \frac{\delta \omega}{\Delta a} \frac{\omega_{(z, 0)}}{2} + \frac{\partial L_{\omega(z, 0)}}{\partial R} \frac{dR}{dz} \right) + \cot \phi \frac{x \cot \phi \cos \phi}{U_0 \pm l_z} \right] \quad (158)$$

the dimensions of the speed responsive device being as defined under Case (1)b, and the stability-equations of higher orders can be expressed in this form.

(c) Taking the same example of a speed responsive device as under Case (1)c, say a ball and conical cup type centrifugal mechanism as there defined, the equilibrium equation becomes,

$$k \cdot x \cdot l_z \cdot \sin \phi - \omega_{(z, 0)}^2 M \cdot R \cdot y = 0$$

the stability-equation of the first order becomes

$$25 \quad \frac{x}{l_z} = \sin \phi \left[\left(\frac{\delta \omega}{\Delta a} + \frac{U}{R} \right) y + \cot \phi \frac{x \cot \phi \cos \phi}{U \pm l_z} \right] \quad (142.A)$$

and so on for higher orders of stability-equations, giving the systems of equations for determining the path of engagement point A^0 relative to the system of coordinates, having its origin fixed to the fulcrum, B , of the lever, and its X-axis along the mid-position of the lever, as explained for Case 1 of the other engagement means.

Embodiments of the present invention, with regard to speed-setting adjustment means effecting, with one actuating motion, adjustment of the dimensions of the spring-lever balancing mechanism, in accordance with the stability-equations given before, can be of the following kinds, or can be combinations thereof, as described by way of example and in some detail with reference to the accompanying drawings hereafter:

(A) The spring-lever balancing mechanism comprises means for guiding said first connection means engaging said spring with the lever to be capable of motion only along a straight line fixed relative to said anchorage, which is immovable, during governing, at the same speed-setting (said straight line being hereafter referred to as the line of action of the spring means), and said first connection engages the lever movably therealong, e. g. by means of a roller, thus embodying the method of engagement in conformity with the relation:

$$60 \quad \frac{dx}{d\beta} = x \cdot \cot \phi$$

as stated before. The adjustment means for a change of speed-setting comprises a first guide-surface mounted on the fixture and being at all points inclined to said line of action, of said spring-means for engaging said anchorage for said spring-means and further means for displacing said anchorage for the spring along said first guide-surface while maintaining the line of action of the spring-means parallel to itself (see Figs. 1, 4, 5, 6, 7, 8 and 9); which adjustment involves a displacement along said lever of the engagement point C therewith of the first connection means from the spring thus adjusting distance $BC = x$, and said displacement of the anchorage of the spring along said first guide-

70

75

75

surface, varying the deflection l_x of the spring at least for the same mid-position of the lever, as well as the dimensions BA^0 and angle β , giving the position of point A^0 in the system of co-ordinates with its origin at fulcrum B, and its X-axis along the mid-position of the lever. Thus x , l_x , BA^0 and β are variable in accordance with the stability-equations. For example, as shown in Fig. 1, both the anchorage for the spring means and the guide-means for the first connection means may be mounted in a guide-carrier, which is displaced parallel to itself for a change of speed-setting.

(B) Irrespective of the method of engagement between the spring-means and the lever, the adjustment means for a change of speed-setting comprises a carrier for the support of the fulcrum of the lever, a secondary guide-surface for adjustably mounting the anchorage of the spring-means on said fixture, which secondary guide-surface extends parallel to the centre-line of the spring means, a transmission means between said carrier for said fulcrum (B) and said anchorage or said spring means, and means for adjusting for a change of speed-setting, the position of said carrier relative to said fixture (see Figs. 6, 7, 8 and 10), which adjustment involves a displacement relative to said fixture of the fulcrum of said lever, thereby adjusting distance $BC=x$ (and distance $BD=y$, though in a geometrically predetermined way for the length BD of the lever constant) and, through said transmission means, a displacement along said secondary guide-surface of said anchorage for the spring, which adjusts the deflection l_x of the spring at least for the same mid-position of the lever, as well as dimensions BA^0 and β , giving the position of engagement point A^0 relative to the system of co-ordinates having its origin fixed to the fulcrum of the lever and its X-axis along the mid-position of the lever. The dimensions l_x , x , BA^0 and β are thus adjustable in accordance with the stability-equations by having suitably shaped slots in the transmission means, adjustment proceeding with one adjustment motion only.

(C) Irrespective of the method of engagement between the spring-means and the lever, the adjustment means for a change of speed-setting comprises: said second connection means between said lever and said sleeve-member of the speed-responsive device with provision (such as a roller) for engaging said lever movably therewith and provision for engaging said sleeve-member movably relative thereto in the direction parallel to the mid-position of the lever, a carrier for said second connection means, a guide-means in said carrier for permitting motion of said second connection means, during governing, only parallel to the direction of motion of said sleeve-member; a secondary guide-surface in said fixture for adjustably mounting said anchorage for said spring-means, said secondary guide-surface extending parallel to the line of action of said spring-means, transmission means between said carrier and said anchorage for said spring means (e. g. a guide-slot in an extension from the carrier, or a secondary lever, as shown), and means for displacing, at a change of speed-setting, said carrier relative to said fixture. Such adjustment involves a displacement along said lever of said second connection means, thereby adjusting the distance $BD=y$, and a displacement along the line of action of said spring-means of the support therefor, which involves

adjustment of the deflection l_x at least for the same mid-position of the lever, as well as adjustment of dimensions BA^0 and β . The dimensions l_x , y , BA^0 and β are thus adjustable, with one adjustment motion for a change of speed-setting, in accordance with the stability-equations, which determine the shape of the slots in the transmission means (e. g. in the extension from the carrier, or in the secondary lever, as shown).

(D) As seen with reference to the example of Fig. 12, with the first connection means between the spring-means and the lever having movable engagement the lever (e. g. through a roller) and being guided so as to be capable of motion only along a straight line fixed during governing at the same speed-setting relative to a then immovable anchorage in conformity with method of engagement according to

$$\frac{dx}{d\beta} = x \cot \phi$$

the spring-means is mounted in a guide-carrier, which mounts said guide-means for the first engagement means at one end, and has a secondary guide-surface for adjustably mounting the anchorage for said spring-means, said secondary guide-surface extending along the line of action of the spring-means. The adjustment means for a change of speed-setting comprises: a first guide-surface mounted in said fixture, for engaging said anchorage of said spring-means, a shaft rotatably mounting said guide-carrier for said spring-means in said fixture, and means for rotationally adjusting, for a change of speed-setting, the position of said guide-carrier relative to said fixture. This adjustment involves adjustment of the angle ϕ between the line of action of the spring means and lever in its mid-position, displacement of engagement point C of the first connection of the spring means with the lever along the lever, and thus adjustment of the distance $BC=x$, and a displacement of the anchorage of said spring means along its first guide-surface in the fixture, which involves displacement of said anchorage along the line of action of the spring-means, and thus adjustment of deflection l_x of the spring-means, at least for the same mid-position of the lever, as well as adjustment of the dimensions BA^0 and angle β , defining the position of point A^0 relative to the system of co-ordinates having its origin at fulcrum B and its X-axis along the mid-position of the lever. Dimensions x , ϕ , l_x , BA^0 and β are here adjusted with one adjusting motion, but since point G of rotation for the guide-carrier is fixed in the fixture, the adjustment of one of said dimensions is geometrically predetermined, leaving four of these dimensions (including l_x) adjustable in accordance with the stability-equations, which supply the shape of the first-guide-surface for the anchorage of the spring-means.

(E) In a construction as defined in the foregoing paragraph (D), the shaft mounting the guide-carrier is also mounted in a carriage, which is movable relative to said fixture during change of speed-setting, apart from the guide-carrier being rotated relative to said fixture, all with one adjusting motion for a change of speed-setting. Then the dimensions l_x , x , ϕ , BA^0 , β are adjustable in accordance with the stability-equations, which supply the shape of the first guide-surface and the motion of point G required.

The order of stability provided by any of the constructions generally described in the foregoing

can be increased to any required order, through using, in combination with any of these spring-lever balancing mechanisms, a provision for adjusting the magnitude of the half sleeve-travel Δa in accordance with the stability-equations, as follows: The half sleeve-travel Δa is adjusted with speed-adjustment in such a way that the ratio

$$\frac{\delta_x}{\Delta a}$$

remains constant for all speed-settings, δ_x being determinable as function of the properties of the engine to be governed for each speed-setting, and by determining the constant dimensions on the right hand sides of the stability-equations of the second, third, fourth and so on stability-equations in accordance with these equations. Without making any further dimensions variable with speed-setting adjustment, these constructions provide as high an order of stability as the order of stability-equations from which variable and invariable dimensions have been calculated, with the minimum number of dimensions adjustable. Such provision comprises, as will be understood with reference to the example of Fig. 5, a transmission member movably mounted in said fixture and connecting to the control-organ of the apparatus to be governed, a third connection means for engaging said lever movably therealong and for engaging said transmission member movably relative thereto in the direction parallel to the mid-position of said lever, a carrier for said third connection means, a guide-means in said carrier for permitting motion of said third connection means only along a straight line fixed relative to said carrier (hereafter referred to as centre-line of said carrier) and inclined to the mid-position of said lever, stops for limiting the motion of said third connection means relative to said carrier therefor, and means for displacing, with the same adjustment motion as actuates the adjustment means for the spring-lever balancing mechanism for a change of speed-setting, said carrier for said third connection relative to said fixture, with the centre-line of said carrier parallel to itself. Thereby the distance of the engagement point of the third connection means with the lever from the fulcrum of the lever is adjusted, and thereby the magnitude of the half-travel Δa of the sleeve of the speed responsive device which corresponds to the same travel between its stops of the said third connection means to said control-organ of the apparatus to be governed, are adjusted in accordance with the stability-equations.

Constructions of higher orders of stability may also be provided by combinations of the embodiments generally described above.

The invention will now be described by way of example and in some detail, reference being had to the accompanying drawings, in which:

Fig. 1 shows a sectional elevation of a variable speed governor showing an example of spring-lever balancing mechanism in which, with only one adjusting motion for a change of speed-setting, the balancing spring is displaced with its centre-line parallel to itself and at 90° to the balancing lever in its mid-position, thereby altering the transmission ratio of the lever and the deflection l_x of the balancing spring in such a way that degree of irregularity δ of the governor varies as a required function of the speed-setting; the example also providing for adjustment of said function;

Fig. 2 shows a part sectional elevation of a detail illustrating an alternative guide-means for the balancing spring of Fig. 1;

Fig. 3 shows a part sectional elevation of a complete variable speed governor embodying an example of adjustable spring lever balancing mechanism of the kind illustrated in Fig. 1, adapted to have the same degree of irregularity δ at speed-settings of the lower part of the range, and varying δ in the higher part of the speed-range.

Fig. 4 shows, in part sectional elevation an alternative detail of the spring-lever balancing mechanism of Fig. 1, with the angle ϕ between the centre-line of the balancing spring and the lever in its mid-position acute, and adjustable apart from changing the speed-setting;

Fig. 5 shows, in part sectional elevation a spring-lever balancing mechanism similar to that shown in Fig. 1, with additional provision for varying the sleeve-travel $2\Delta a$ of the centrifugal mechanism during change of speed-setting; which provides any required high order of stability with fewest dimensions adjustable;

Fig. 6 shows, in sectional elevation, a variable speed governor comprising an embodiment of spring-lever balancing mechanism in which, with only one adjusting motion for a change of speed-setting, the transmission ratio of the lever is changed by adjustment of the position of its fulcrum, together with the deflection of the balancing spring, which is arranged with its centre-line normal to the primary lever in its mid-position, being altered by a secondary lever in such a way that the degree of irregularity remains constant for all speed-settings.

Fig. 7 shows, in sectional elevation, a spring lever balancing mechanism of the kind illustrated in Fig. 6, but having a more general adjustment mechanism (slotted slide) for the deflection of the balancing spring, such that the degree of irregularity varies on any required function of the speed-setting.

Fig. 8 shows, in part sectional elevation, an adjustable spring lever balancing mechanism similar to that shown in Fig. 6, but having the angle ϕ between the non-rotatable centre-line of the balancing spring and the balancing lever in its mid-position an acute angle, the mechanism being adapted to provide δ constant at all speed-settings;

Fig. 9 shows, in part sectional elevation an alternative detail of the adjustment mechanism of Fig. 8, with provision for varying the degree of irregularity δ as a required function of the speed-setting, and means for adjusting the initial value of δ ;

Fig. 10 shows, in part sectional elevation, an adjustable spring lever balancing mechanism similar to that shown in Fig. 7, with additional provision for varying the sleeve-travel $2\Delta a$ of the centrifugal mechanism during change of speed-setting;

Fig. 11 shows, in part sectional elevation, a governor embodying an example of spring lever balancing mechanism, in which, for a change of speed-setting, the point of action of the sleeve of the centrifugal mechanism on the balancing lever is displaced, together with a change of deflection of the balancing spring, which remains at 90° to the lever in its mid-position all with one adjusting motion, such that the degree of irregularity is varied as a required function of the speed-setting;

Fig. 12 shows, in part sectional elevation, a

spring-lever balancing mechanism in which for a change of speed-setting the carrier for the balancing spring-means is rotated, thereby, with one adjusting motion, the distance x between the fulcrum of the primary lever and the point of action of the balancing spring thereon is adjusted, the angle ϕ between the centre-line of the balancing spring-means and the lever in its mid-position is adjusted, and the deflection l_x of the balancing spring from its unstrained length U_0 is adjusted, for varying the degree of irregularity δ of the governor as a required function of the speed-setting.

Fig. 13 shows an alternative detail of Fig. 12, with a curved balancing lever;

Fig. 14 is a diagrammatic drawing required in connection with the general description of the present invention.

The variable speed governor shown in Fig. 1 illustrates an embodiment of spring-lever balancing mechanism in which, for a change of speed-setting, the distance y between the fulcrum B and the point of engagement D of the sleeve with the lever remain unchanged, the transmission ratio of the lever being changed by adjustment of the distance $BC=x$ between said fulcrum B and the point of engagement C of the balancing spring of the lever, proceeding with the angle only between the centre-line of the spring and the lever in its mid-position the same at all speed-settings (spring displaced parallel to itself) and with a corresponding change in the deflection l_x of the balancing spring such that the degree of irregularity δ varies as a desired function of the speed-setting, $\delta=f_1(\omega_{(x,0)})$. The example of spring-lever balancing mechanism also has provision for varying the function as which the degree of irregularity δ changes over the range of speed-settings.

In Fig. 1, a centrifugal mechanism of any suitable type, acting as speed responsive device, is indicated diagrammatically at 12, mounted on governor-shaft 11 and the governor-casing 13, the governor shaft being rotatable by means of flange 14, which is adapted to be connected to the shaft of an engine to be governed. The sleeve-member 15 of the centrifugal mechanism is movable along shaft 11 during governing action.

The spring-lever balancing mechanism comprises: the lever, with a yoke part 17 and a straight arm 19, fulcrummed on axle 18 in the governor casing 13, the tension spring 21, the anchorage 24 for the one end of spring 21, which support is immovable during governing action at the same speed-setting, the connection means 22 between the other end of spring 21 and part 19 of the lever, engaging said arm 19 by means of roller 23, and connection means between the yoke-part of the lever, 17, which extends on both sides of sleeve 15, said second connection means being formed by two diametrically oppositely situated pins 16 on sleeve 15, engaging the forked ends of yoke arms 17 of the lever. The means for effecting adjustment of the transmission-ratio of the lever together with an adjustment of the anchorage 24 of the spring 21 for a change of speed-setting are as follows:

The first connection means 22 between the end of the spring 21 and the lever-arm 19 is guided relative to a carriage 100 for anchorage 24, which is immovable during governing at the same speed-setting, by a guide-means comprising fork 47 fixed on carriage 100, and each respectively engaging one prong of said fork, two rollers 46

mounted on an arm 45, which is fixed to connection means 22, the centre-line of the fork being arranged parallel to the centre-line of the spring, so that engagement piece 22 for the one end of the spring can move relative to the anchorage for the spring only along the line of action of the spring.

The anchorage 24 for the other end of the spring, which is slidably mounted on carriage 100 between the secondary guide-surfaces 110 extending parallel to the centre-line of the spring, engages, by means of a pin 98, a curved first guide-surface which is formed by the curved slot 99 in the member 104, which is mounted in the governing casing. The carriage 100 for anchorage 24 is itself slidably mounted in the governor-casing 13 between a third straight set of guide-surfaces 111, extending normally to the centre-line of the spring means, and is further engaged by a screw 102 mounted in casing 13, the said screw being rotatable from outside the casing by means of milled knob or toothed wheel 103. This method of moving the carriage 100 is indicated here only by way of example, it being understood that any other method of displacing carriage 100 and then keeping it in a desired position, is equally well applicable. The member 104 carrying the curved guide-slot 99 for anchorage 24 is pin-jointed at end 106 to the governor casing 13 (or to a part fixed to casing 13), and has at its other end a forked end engaging a pin 108, which is fixed in a block 107. The block 107 is fixed relative to the casing during governing and ordinarily also during a change of speed-setting, being held between surfaces 112 by screw 109 mounted in the casing. If, however, it is required to adjust the disposition of guide-slot 99 relative to casing 13, in order to influence the function, according to which the degree of irregularity is to vary over the range of speed-settings, as explained hereafter, the block 107 can be moved relative to the casing 13 by rotation of screw 109 from outside the casing 13, the head of screw 109 being accessible outside the casing to be rotated by means of a suitable key.

Similar provision, or other suitable provision, may also be made for altering the position of end 106 of the member 104 relative to the casing, so that, member 104 can be displaced parallel to itself in the direction of the line of action of the spring. This enables the governor to take spring of different unstrained lengths U , while the shape and disposition of the curve described by the end A of the deflection of the spring, set off from point C, and corresponding to the curve of slot 99, are unchanged, thus bringing about the same "irregularity-characteristic" of the governor with spring of different unstrained lengths U_0 , or enabling adjustment to be made to lengthening of length U_0 of a spring after prolonged use, to maintain the same characteristic.

Fig. 2 shows an alternative detail of a guide-means arranged inside the spring, fork 37 being fixed on anchorage 24, and being engaged by rollers 96 on extension 95 from the first connection means 22. Its function corresponds to that of the guide-means described in Fig. 1.

The example of adjustable spring-lever balancing mechanism operates as follows:

During governing at the same speed-setting, when the lever 17-19 rocks about fulcrum axle 18, corresponding to the motion of sleeve 15 of the centrifugal mechanism, the connection means

22 of the balancing spring 21 with the lever arm 19 moves along the centre-line of the spring, it being only capable of such motion due to the fork-roller guide-means, and roller 23 of the first connection means 22 has small displacements backwards and forwards along lever arm 19. Due to the rollers 46 in the guide-means, which are of relatively large diameter, as is also roller 23, the mechanism has from these parts only rolling resistance against governing motion, which is extremely small.

The arm 20 mounted on fulcrum-axle 18 outside the casing serves to transmit the governing motion to the control-organ of the engine to be governed.

For a change of speed-setting, rotation of screw 102 by means of knob 103 outside the casing moves the carriage 100 along its guide-surfaces 111, parallel to the lever 19 in its mid-position. As both ends of the spring 21 are guided to be capable of motion relative to carriage 100 only along the line of action of the spring, due to anchorage 24 being mounted in guides 110, and first connection means 22 on the fork-roller guide-means, the line of action of spring 21 is moved parallel to itself, involving displacement of the roller 23 along the lever arm 19, and thus the adjustment of distance x . Simultaneously, the anchorage 24 for the spring is displaced along the curved slot 99, forming the first guide-surface, the component of this displacement of anchorage 24, which is parallel to the line of action of spring 21, changing the deflection l_x of the spring.

The construction described with reference to Fig. 1 is an embodiment of the spring-lever balancing mechanism of this invention in accordance with Equations (128), (125) and (129) for the particular case that the distance $BD=y$ is constant and that angle ϕ is constant and 90° so that, for any speed responsive device of known properties, the equations give the shape of the guide-slot 99 with reference to the right angles system of co-ordinates having its origin at the fulcrum B of the lever, its X-axis along the mid-position of the lever and its U_x -axis normal thereto.

Consideration of the equations will show that for the special case of ϕ the same for all speed-settings,

is constant, for which case then the shape of guide-slot 99, i.e. the shape of the first guide-surface for the spring-anchorage becomes a straight line, which encloses an angle $\beta^0 = BCA$ (as distinct from angle $\beta = BCA^\circ$) with the lever in its mid-position, and passes through a point B^0 , which is situated on the parallel to the centre-line CA° of the spring, at a distance

$$BB^0 = AA^0 = U_0$$

from fulcrum B.

The construction is further adapted to take springs of different unstrained lengths U_0 for the same shape and disposition of slot 99, as the member 104, carrying slot 99, is made displaceable parallel to itself, by providing a further screw adjustment at the end 106 of member 104, so that both the ends 107 and 106 of the member can be displaced together parallel to the centre-line of the spring-means. Displacement of only one end of the member causes a rotary change of disposition of slot 99, which will be seen from

the first stability-equation to cause a different development of the degree of irregularity over the range of speed-settings.

Fig. 3 shows, in a variable speed centrifugal governor, a further example of a spring lever balancing mechanism, in which a change of speed-setting is carried out by displacement of the balancing spring means with its centre-line remaining parallel to itself, this example showing a very simple construction with the angle ϕ between the lever in its mid-position and the centre-line of the spring means equal to 90° , and provision for effecting that the degree of irregularity of the governor remains the same at all speed-settings.

A centrifugal mechanism of a suitable type is indicated diagrammatically at 12, mounted on governor shaft 11 and casing 13, shaft 11 being rotatable by means of flange 14. The sleeve 15 of the centrifugal mechanism is movable along shaft 11 with changes of shaft-speed. The spring-lever balancing mechanism comprises angled lever 17-19, fulcrumed on axle 18 in the housing 13, the tension spring 21, the anchorage 24 for the one end of spring 21, which is immovable during governing at the same speed-setting, the connection means 22 between the other end of spring 21 and arm 19 of the lever, engaging said arm through roller 23, and a second connection means between the yoke-part 17 of the lever and sleeve 15, formed by diametrically oppositely situated pins 16 on said sleeve. Anchorage 24 for spring 21 is mounted on guide-surfaces 23 in casing 13, guide-surfaces 23 being straight and at constant angle β^0 to the mid-position of the lever-arm 19, and is movable along said guide-surface for changes of speed-setting by screw 29, rotatable through wheel 30. Control-lever 20 is mounted on axle 18 outside casing 13. The means for guiding member 22 relative to support 24 is a fork-roller mechanism as described for Fig. 1, like numerals denoting like parts, with fork 47 directly fixed to anchorage 24.

During governing at any speed-setting, the spring-lever balancing mechanism operates as follows: When the lever rocks, the connection means 22 of the spring 21 with the lever 19 can only move along the line of action of the spring, because member 45 with its rollers 46 is constrained to move between the two prongs of fork 47 parallel to the line of action of the spring, and roller 23 therefore moves along the part 19 of the lever.

For a change of speed-setting, rotation of screw 29 by knob 30 moves the anchorage 24 along the straight guide-surfaces 23 in the casing, and, as the guide-means only permits motion of connection means 22 relative to anchorage 24 along the centre-line of the spring, the roller 23 is displaced along lever 19 with the line of action of the spring remaining parallel to its original direction in all speed-settings, thus changing the distance $BC=x$ between the point of engagement C of the spring-means with the lever and the fulcrum B of the lever; and the deflection l_x of the spring, for the middle, or for any other position of the sleeve is changed simultaneously by the component along the centre-line of the spring of the displacement of anchorage 24 along the straight guide-surfaces 23. Lever 19 ends in a curved portion 59.

As already explained parallel displacement of the centre-line CA° of the spring-means, with displacement of the point of engagement A° be-

tween the spring means and its otherwise immovable anchorage 24 along a straight line guide-surface B^0A^0 , for which point B^0 is situated on a line through the fulcrum B, and parallel to the centre-line of the spring, at a distance $BB^0 = U_0$, the unstrained length of the spring means from fulcrum B, and which guide-surface B^0A^0 encloses a constant angle β^0 with the lever-part 19 in its mid-position, effects that the degree of irregularity δ_ω is constant over the whole range of speed-settings. The magnitude of δ_ω which is kept constant over the range of speed-settings, is seen from the equations to depend on the magnitude of angle β^0 , of the arm $DB = y$ (measured normally to the direction of motion of sleeve 15 of the centrifugal mechanism), and on the sleeve-travel $Z\Delta\alpha'$.

For the speed-settings, for which the point of engagement C is on the curved part 59 of the lever, δ varies according to a required function of $\omega_{(x,0)}$, the required curvature of the lever-part 59 having been determined in accordance with the equations.

Fig. 4 shows a detail illustrating a modification of the spring lever balancing mechanism shown in Fig. 1, like numerals denoting like parts, the difference being that here provision is shown to adjust the centre-line CA^0 of the spring means to any required angle ϕ to the lever in its mid-position, which angle is to be kept constant for all speed-settings. Here the carriage 100 for the spring-anchorage 24, instead of being of one piece, as in Fig. 1, comprises a separate part 113 for carrying the spring-means with the guide-means therefor, including the anchorage 24 for the spring, which is slidably mounted between the secondary guide-surfaces 110, and the fork-roller guide-means for the engagement piece 22. The part 113 is mounted on the base 100 of the carriage by some suitable means, here indicated by way of example as a locked nut, such that the centre-line of the spring means can be set at any desired angle ϕ to the lever-arm 19 in its mid-position. The mechanism operates exactly as that described with reference to Fig. 1, the possible adjustment of angle ϕ being another method of adjusting the function, according to which $\delta_{x(x,0)}$ varies over the range of speed-settings.

The detail of Fig. 4 applied to the mechanism of Fig. 1 makes this an embodiment of a spring-lever mechanism in accordance with the Equations (54), (144) and (155). Consideration of the equations shows that initial adjustment of angle ϕ changes the initial value of δ which is varied as a required function of the speed-setting with a suitably curved guide-slot 99, and which is kept constant over the speed-range with a straight guide-slot 99.

Fig. 5 shows, in sectional elevation, an example of an embodiment of a spring-lever balancing mechanism in which the speed-setting is changed by displacement of the balancing spring parallel to itself, with special attachment for varying the sleeve-travel of the centrifugal mechanism together with the speed-setting to suit a required development of the degree of irregularity $\delta_{x(x,0)}$ over the range of speed-settings and, more particularly, to provide a construction of any required higher order of stability than the spring-lever mechanism it is applied with, as stated in the general description. This special attachment may be applied with any of the constructions described in this specification.

The spring-lever balancing mechanism here shown is substantially the same as that already

described with reference to Fig. 1, like numerals denoting like parts; it only differs from that of Fig. 1 in the shape of the guide-slot 99 for the anchorage 24 of the balancing spring-means, and in the method of engagement between the sleeve 15 of the centrifugal mechanism and the balancing lever, which is by means of a frame 121 extending from said sleeve and carrying a roller 639 for engaging said lever.

The governor further has, instead of the lever 20 fixed on the fulcrum axle 18, as in Fig. 1, a different mechanism for engaging the control-organ (or servo-motor) of the engine to be governed, which mechanism also embodies the provision for varying the sleeve travel with change of speed-settings, as follows:

The balancing lever has an extension 642 beyond the point of engagement D therewith of the roller 639 from the sleeve, and this extension is engaged by two rollers 643 of a member 641. This member is guided by means of two further rollers 643 in the guide-surfaces 644 of a carrier 640, so that this member 641 is only capable of motion in the direction normal to the lever in its mid-position. Further, this member engages by means of a fork 645 extending parallel to the balancing lever in its said position, a pin 646 at the end of a rod 647, which leads out of the governor-casing to the control-organ (or servo-motor) of the engine to be governed, member 641—645 representing the "third" connection means, engaging both the lever and the control-rod leading to the control-organ of the engine to be governed. The screws 649 and 650 set in the carrier 640 limit the motion of the member 641 in the direction normal to the lever in its mid-position, thereby also limiting the motion in that direction of the point on the balancing lever, which is engaged by the rollers 643, and thus the travel of the sleeve of the centrifugal mechanism.

The carriage 640 is mounted on a guide-surface 652, which extends parallel to the lever in its mid-position, and is movable for a change of speed-setting, by a displacement means shown diagrammatically at 653, actuated by a continuation 654 of the screw 102, which also moves the spring-carriage 100 of the spring-lever balancing mechanism. Displacement of the carrier 640 is seen to change the position, at which rollers 643 engage the lever, and hence, with the distance between the stops 649 and 650 constant, the magnitude of the sleeve-travel. Depending on the requirements, the displacement may be such as to effect a displacement of the carrier in the same direction as that of the spring-carrier 100 with the same actuating motion of knob 103, or in the opposite direction.

It will be understood that the screws are merely shown as diagrammatic representations of the means for moving both the carriers 100 and 640 in any desired way respectively for a change of speed-setting, and for keeping these carriers fixed in their respective positions for governing at the same speed-setting, and that any suitable provision for bringing about this effect may be applied.

The provision shown operates as follows:

For a change of speed-setting, say an increase in speed-setting, the screw 102 moves the carrier 100 to the right, and carrier 640 to the left. This displacement of carrier 100, as has already been explained with reference to Fig. 1, increases the speed-setting together with decreasing the degree of irregularity, due to the shape of the guide-slot 99, even with the same sleeve-travel,

while due to the carriage 640 being moved to the left, the half sleeve-travel Δa is decreased, as may be required by the stability equations.

The value of the half sleeve-travel Δa at any adjustment of the mechanism determined by the half distance i between the stops 649 and 650, by an adjustable distance e between the point of engagement of the rollers 648 with the lever and the fulcrum B of the lever and by a fixed distance y between the point of engagement D between the sleeve-roller 639 and the lever and the fulcrum B (18) of the lever, is

$$\Delta a = \frac{i}{e} y \quad (149)$$

which shows Δa to decrease with increasing distance e i. e. with the speed-setting being increased, so that, for example in accordance with the required stability condition according to the Equation (86) δ_x decreases with the speed-setting being increased.

Since the mechanism for adjusting the sleeve-travel serves at the same time to transmit the governing motion to the control-organ of the engine to be governed, as has to be the case since the motion of the control-organ corresponding to a full sleeve-travel has to be the same also for different magnitude of sleeve-travel, the adjustment of the sleeve-travel as shown in this example has also an effect on the development of the control-resistance effective at the sleeve, and hence on the degree of insensitivity of governing.

An important property of the above attachment for varying $2\Delta a$ emerges from consideration of the stability-equations of the 2nd order (155), of the 3rd order (156), of the 4th order (157), which are given in evaluated form for the example of a ball-and-conical-cup speed responsive device earlier on.

It is seen generally that by adding the attachment to a construction with a certain order of stability at all speed-settings, and thereby providing an additional dimension variable with speed-setting adjustments in accordance with the stability-equation of the next higher order, the order of stability of this construction is increased by unity, as would generally be achieved by, say, a combination of any of the other constructions shown which would provide an additional dimension capable of adjustment in accordance with this stability-equation.

However, consideration of the Equations (155), (156) and (157), for the particular case of the variation of the sleeve-travel $2\Delta a$ with speed-setting adjustment shows that, if Δa is varied in such a way that

$$\frac{\delta_x}{\Delta a}$$

remains constant for all speed-settings

$$(\delta_x = f(\omega_{x,0}))$$

being known as requirement of the engine to be governed), then the construction can satisfy all the stability-equations of higher orders (in which

$$\frac{\delta_x}{\Delta a}$$

only occurs on the L. H. S.'s) merely by the determination of one of the invariable dimensions of the construction from each of these higher-order stability-equations.

Thus, by providing a construction of the first

order of stability as that shown in Fig. 1 with the attachment for varying Δa designed to provide

$$\frac{\delta_x}{\Delta a}$$

constant for all speed-settings, and by designing the invariable dimensions of this construction in accordance with the stability-equations of the 2nd, 3rd, 4th order, one obtains a construction providing 4th order of stability with required development of δ_x over the speed-range with the minimum number of dimensions variable during speed-setting adjustment, i. e. with the simplest construction.

Whereas generally the higher the order of stability, the greater the number of dimensions adjustable with speed-setting in accordance with the stability-equations of the higher orders has to be in any construction, i. e. the more complicated the construction has to be, this attachment for varying the sleeve-travel Δa thus provides the exceptional case of yielding as high an order of stability as required with the minimum number of dimensions adjustable for speed-setting.

The variable speed-governor shown in Fig. 6 illustrates a simple embodiment of spring-lever balancing mechanism in which for a change of speed-setting, the transmission ratio of the lever is changed by adjustment of the distance y between the fulcrum B of the lever and the point of engagement D between this lever and the engagement means from the sleeve through, in this example, a displacement of fulcrum B along the lever, the angle $\phi=90^\circ$ between the centre line of the pin-jointed balancing spring and the lever in its mid-position remaining the same at all speed-settings, and in which simultaneously a change of the deflection l_x of the balancing spring is effected, such that the degree of irregularity of $\delta_{x(x,0)}$ remains the same at all speed-settings, or varies as a required function.

The centrifugal mechanism of a suitable type is indicated diagrammatically at 12, mounted on governor shaft 11 and casing 13, shaft 11 being rotatable by means of flange 14. The sleeve 15 of the centrifugal mechanism is movable along shaft 11 with changes of shaft-speed. The spring-lever balancing mechanism here comprises straight lever 211—213, fulcrumed on axle 219, which engages slot 212 of the lever; the tension spring 215 the anchorage 218 for the one end spring 215, which is immovable during governing at the same speed-setting; the hook-connection 216 for the other end of the spring 215 with arm 211 of the lever, engaging said lever at eye 217; and the connection between the yoked part 213 of the lever and sleeve 15 of the centrifugal mechanism.

This second connection means is formed by two diametrically oppositely situated pins 16 on the sleeve 15, which respectively rotatably engage the slides 240, which are slidably mounted in the slotted ends 214 of the yoke-arms 213 of the lever, the slides 240 being elastically held in position by the two small leaf springs 241 shown, or by alternative elastic means.

The fulcrum axle 219, which engages the lever in its slot 212, is here mounted in the carrier 220, which is displaceable along the direction parallel to the mid-position of the lever by means of screw 221 mounted in the casing 13 and in partition walls 223 and 222 thereof, and rotatable by means of wheel 224, this provision forming part of the means for changing the speed set-

ting by adjusting the distance $BD=y$, and incidentally, since the fulcrum is displaced while the spring remains stationary, the distance x as well, thus changing the transmission ratio of the lever. The means for effecting simultaneous adjustment of the deflection l_x of the spring comprises the secondary lever, or a symmetrically positioned pair of secondary levers, 226, fulcrumed in casing 13 on axle 227, which is situated on the parallel to the centre-line of the balancing spring through the point of engagement D of the lever with sleeve, said secondary lever 226 engaging pin 229 on carriage 220 by means of slot 228, and further engaging with the same straight slot the pin 230 on anchorage 218 for the balancing spring 215. Anchorage 218 is further guided to be capable of motion only along the centre-line of balancing spring 215 on guide-surface 223 fixed to casing 13. The carrier 220 is guided by guide-surfaces 232, extending parallel to the lever in its mid-position, carrier 220 engaging said guide-surfaces by means of slide 231. Lever 28, connecting to the control-mechanism of the engine or the like to be governed, is mounted on axle 123 in casing 13 and engages the sleeve 15 by means of yoke-arm 124, which engages the pins 146 on the sleeve.

For change of speed-setting, rotation of screw 221 by means of knob 224 displaces the carrier 220 parallel to the lever in its mid-position, moving fulcrum axle 219 and pin 229 parallel to one another. The motion of fulcrum axle 229 adjusts distance y , and also distance x , thus adjusting the transmission ratio of the lever, while the parallel motion of pin 229 rotates secondary lever 226 about its fulcrum 227, and thereby displaces the anchorage 218 along the centre-line of the spring, thus adjusting the deflection l_x of the balancing spring, all this being caused by the same adjusting motion of the wheel 224, and keeping the degree of irregularity $\delta_{x(x,0)}$ the same, if the slot 228 is straight, as explained hereafter, of varying $\delta_{x(x,0)}$ according to a desired function over the range of speed-settings if the slot has a suitable curve.

The connection means between the pins 16 on the sleeve and the yoke-parts 213 of the lever, having the pins engaging the elastically mounted slides 240 in the slotted ends 214 of these arms 213, serves the purpose of transmitting the sleeve-motion to the lever during governing, while at the same time taking up elastically the relative motion between the pins 16 on the sleeve, which have a straight line motion, and the end of the lever, which describes the arc of a circle about the fulcrum B, in such a way, that a minimum of frictional resistance against governing motion is caused. Further, during change of speed-setting, when the fulcrum pin is displaced along the lever, this engagement means holds the lever substantially in position relative to the sleeve.

Fig. 7 shows a spring-lever balancing mechanism similar to that shown in Fig. 6, with an example of an alternative means for effecting the adjustment of the deflection of the balancing spring during change of speed-setting, the means for adjusting the transmission ratio of the lever being the same, for keeping the degree of irregularity $\delta_{x(x,0)}$ the same at all speed-settings, or having it varying according to a desired function of the speed-setting.

The spring-lever balancing mechanism is largely similar to that described with reference to Fig. 6, like numerals denoting like parts, except that the connection means between lever 213 and

sleeve 15 of the centrifugal mechanism here comprises frame 121 fixed to sleeve 15, this frame carrying the pin 16 for engaging fork 214 of the lever, which enables the minimum value of distance $BD=y$ to be smaller. Further instead of the secondary lever mechanism for adjusting the deflection of balancing spring 215, the carrier 220 here has fixed to it an extension 251 provided with a curved slot 252 for engaging pin 230 of anchorage 218 for the balancing spring. Thus, for change of speed-setting, displacement of carrier 220 displaces fulcrum pin 219, thus adjusting the transmission ratio of the lever, while slot 252 displaces support 218 along the centre-line of the spring. The curvature of slot 252 can be made such that the motion of support 218 with change of speed-setting is the same as that given it by the secondary lever in the example of Fig. 6, whereby $\delta_{x(x,0)}$ is kept the same at all speed-settings, as will be explained or it may be given any required shape for making $\delta_{x(x,0)}$ vary according to a desired function with change of speed-setting.

In this example, connection means between the pin 16 on the frame fixed to the governor sleeve, and the part 213 of the lever is shown, which is a modification of that shown in Fig. 5. Here the end 214 of the lever is forked along the centre-line of the lever, and the fork directly engages the pin 16 on the sleeve-extension.

One of the prongs has a projection 243, at the end of which is mounted a leaf spring 244, so shaped as to engage the side of pin 16 at the open side of the fork, and the other prong has a shorter leaf spring 245, which engages the other side of pin 216.

Hence, for governing motion, the pin 216 is held at top and bottom between the prongs of fork 214 of the lever, so that the sleeve-motion is directly transmitted to the lever, while at both sides the pin 216 is held elastically by the leaf springs 244 and 245, which permit the relative motion along the centre-line of the lever between this and the pin 216, which is required due to the sleeve describing a straight line motion, and the lever the arc of a circle about the fulcrum B.

It will be noted that the outer leaf spring 244 is longer than leaf spring 245, and that spring 244 is only fixed at its extreme end to the projection 243, so that spring 244 is of greater elasticity than spring 245, which is arranged because during governing, starting from the mid-position shown, the pin 216 will move against spring 244 when the lever leaves the mid-position.

A stop 246 for this spring is provided on the other prong of the fork 214, and the inner wall 247 acts as a stop for leaf spring 245, to prevent the pin 216 being displaced too far relative to the lever, during changes of speed-setting when the fulcrum pin is moved relative to the lever.

Fig. 8 shows a spring lever balancing mechanism for keeping the degree of irregularity $\delta_{x(x,0)}$ the same at all speed-settings, similar to that shown in Fig. 6 and described with reference thereto, like numerals denoting like parts, the difference being that here the angle ϕ between the centre-line of the balancing spring 215 and the lever in its mid-position is not 90° , but an acute angle, brought about by having the guide-rails 321 for the anchorage 218 of the balancing spring at that angle to the lever in its mid-position. To correspond with that, the carrier 320 for the fulcrum pin 219 (point B) and for the pin 229 (point B⁰) for adjusting the secondary

lever, has its centre-line arranged parallel to the line of action of the balancing spring 215.

In this example the engagement means between the lever and the sleeve is similar to that already described with reference to Fig. 6, like numerals denoting like parts, with the additional refinement that the position of side-wall 242 of the slotted end 214 of the lever is made adjustable by means of screw 248 in order to allow the compression of the two small leaf springs 241 to be adjusted. The function of this connection means is as already described with reference to Figs. 6 and 7.

Fig. 9 shows a detail of a modification of the spring-lever balancing mechanism shown in Fig. 8, in which the secondary lever 228, instead of having a straight line slot, has a curved slot 241, whereby, as explained, the degree of irregularity $\delta_{x(x,0)}$ changes from one speed-setting to another according to a function dependent on the shape of the curve, instead of remaining the same as would be the case with a straight slot.

A further modification shown in Fig. 9, in which otherwise the same numerals denote the same parts as in Fig. 8, consists in a provision for adjusting the position of fulcrum pin 227 (point E⁰) of the secondary lever, which comprises mounting 330 for fulcrum pin 227, in which screw 331 is rotatably fitted, the screw 331 being threaded in holder 333 fixed to casing 13. Adjustment of screw 331 by means of milled knob 332 moves the fulcrum pin 227 (E⁰) along the centre-line of screw 331, so that, as explained in the following, this adjustment changes the value of the degree of irregularity $\delta_{x(x,0)}$, which is to be kept constant for all speed-settings, for a spring lever balancing mechanism with a straight slot 228 in secondary lever 226, as in Fig. 8, or which is to be varied according to a predetermined function with change of speed-setting, for a construction of spring lever balancing mechanism with a curved slot 241 in lever 226, as shown in Fig. 9.

It will be understood that the modifications illustrated in Fig. 9, are not only applicable to the example of spring lever balancing mechanism shown in Fig. 8, but are equally well applicable to the other examples of spring-lever balancing mechanism shown, which comprises secondary levers.

The constructions described with reference to Figs. 6, 7, are embodiments of the general spring-lever balancing mechanism in accordance with the Equations (141), (142), and those of Figs. 8 and 9 in accordance with the Equations (128), (125), (129) together with the particular condition of the method of adjusting the transmission ratio of the lever, viz. $y=b-x$ (139), for any speed responsive device.

With the properties of the speed-responsive device known, these equations yield the equation of the path of point A⁰ relative to a system of coordinates with its origin at fulcrum B and its X-axis along the mid-position of the lever. The shape of this path is traced out by guide-slot 252 of the construction of Fig. 7.

The secondary lever constructions of Figs. 6 and 8 can be seen from the equations, suitably transformed, to be alternative means for tracing out such paths of point A⁰ in this system of coordinates. The equations show that for the secondary levers having straight slots, as in Figs. 6 and 8, the degree of irregularity δ will be con-

stant over the range of speed-settings, while with a curved slot as in the modification of Fig. 9 a required variation of the degree of irregularity δ over the range of speed-settings will be produced.

As further shown on Fig. 9, the provision for varying the normal distance of the fulcrum-point E⁰ of the secondary lever from the line B⁰C⁰ effects an adjustment of the initial value of δ .

In Fig. 10, the spring-lever balancing mechanism is exactly that already described with reference to Fig. 7, like numerals denoting like parts, differing from Fig. 11 only in the method of engagement of the member actuating the control-organ. The means for varying the sleeve-travel $2\Delta a$ with change of speed-setting comprises two stops 601 formed by screws in fixtures 602 in the casing, and adjustable by means of milled heads 603. The primary lever has an extension 607 extending beyond its point of engagement with the sleeve of the centrifugal mechanism to a position between these stops. On the line normal to the lever in its mid-position and connecting these stops the extension 607 of the primary lever has a slot 606, for engaging a pin 605 on the member 604 actuating the control-organ of the engine to be governed.

For governing at any speed-setting, for which y is the adjusted distance BD, while j is the constant distance along the lever between the point of engagement D of the sleeve with the lever and the stops, and i is the distance from the mid-position of the lever to a stop, normally to the lever in its mid-position that the half sleeve-travel

$$\Delta a = \frac{i}{(j+y)} \cdot y \quad (150)$$

Thus, with increasing y , which corresponds to the speed-setting being reduced, the sleeve-travel $2\Delta a$ is increased, which corresponds to an increasing degree of irregularity.

The construction shown has a particular advantage with regard to the development of the degree of insensitivity over the range of speed-settings, in that the resistance of the control-organ, which is the same for all speed-settings, due to its action on the primary lever at the stops, and hence with different arms for different speed-settings, exerts a greater resistance moment for a smaller speed-setting (when y is larger) than at a higher speed-setting (when y is smaller). This effects an increase of the degree of insensitivity ϵ_x with falling speed-setting, which is proportional to more than the second power of the ratio of the highest speed-setting to any lower speed-setting for which ϵ_x is considered. This development will approximate to the development of ϵ_x required on a reciprocating engine, for fulfilment of the condition that the degree of insensitivity should be as small as possible while not being less than the degree of speed-fluctuation ξ of the rotating masses of the engine, which, due to the influence of the reciprocating masses, increases with falling speed-setting proportionally to more than the second power of said speed-ratio.

It must be stated that for the stops on the other side of the fulcrum, i. e. an extension extending beyond the point of engagement C of the spring with the lever, and the engagement of the actuating member for the control organ at that position, the resistance at the sleeve due to the constant control organ resistance would fall with falling speed-setting which provides for an undesirable development of the degree of insensitivity over the range of speed-settings, as already

explained, which may lead to dancing or hunting of the governor at the low end of the speed-range, or it may make the governor insensitive at the high end of the speed-range, or may have both these harmful effects, thus making the governor useless for variable speed applications.

The variable speed governor shown in Fig. 11 illustrates another embodiment of spring-lever balancing mechanism in which, for a change of speed-setting, the transmission-ratio of the lever is changed by adjustment of the distance y between the fulcrum B of the balancing lever and the point of engagement D between this lever and the engagement means from the sleeve, through displacement of point D along the lever, the angle $\phi=90^\circ$ between the centre-line of the spring and the lever in its mid-position remaining the same at all speed-settings, together with a corresponding change of the deflection l_x of the balancing spring, such that the degree of irregularity $\delta_{x(x,0)}$ varies as a required function of the speed-setting.

The centrifugal mechanism of a suitable type is indicated diagrammatically at 12, mounted on governor shaft 11 and casing 13, shaft 11 being rotatable by means of flange 14, as previously described. The spring-lever balancing mechanism comprises lever 341, fulcrumed at 342(B) in housing 13, the tension spring 215, anchorage 218 for one end of spring 215, said anchorage being immovable during governing at the same speed-setting, the first connection means between the other end of spring 215 and the lever, which comprises the guided engagement piece 216, contacting the lever through roller 347, at C, and the second connection means between the lever and the extension 121 and 343 of the sleeve 15 of the centrifugal mechanism.

The second connection means 345 is mounted in a carrier 346, which engages two guide-walls 351, disposed parallel to lever 341 in its mid-position, by means of shoes 350, and is movable therealong by means of screw 348, which is mounted in casing 13 and is rotatable by means of milled knob 349.

Carrier 346 ends in two guide-rails 352, directed parallel to governor spindle 11, between which run two rollers 353 of engagement means 345, enabling this to move up and down parallel to the governor shaft axis with motion of the governor sleeve. Connection means 345 has at its other end a roller 354, by means of which it engages the balancing lever 341, and, extending parallel to the mid-position of the lever, a fork 355, which engages pin 344 of the extension 343 of the governor sleeve 15.

Due to this provision, pin 344 transmits the motion of the sleeve during governing to the engagement means 345, which can then only move parallel to the governor spindle 11, and this, in turn, transmits this sleeve motion to the lever 341 at the point of engagement D.

Further, when carrier 346 is displaced by adjustment of screw 348 to effect a change of speed-setting, the engagement means 345 is moved thereby along the lever 341, displacing roller 354, and thus point of engagement D, along the lever, and pin 344 in fork 355. Thus, by means of the connection means 345 described, the motion of the sleeve is transferred unhindered to the lever 341 at different speed-settings, and even during change of speed-setting, which can thus proceed simultaneously with governing.

The means for effecting adjustment of the deflection l_x of the balancing spring together with change of transmission ratio of the lever com-

prises secondary lever 358, fulcrumed by means of pin 360 (at point E⁰) in housing 13, and having pin 357 (D⁰) fixed to carriage 348, and pin 230 fixed to the anchorage 218 for the balancing spring, which has a curved slot 359 for engaging pin 357 and a straight line part 356 for engaging pin 230 (A⁰). Anchorage 218 of the balancing spring is guided along wall 223, normally to the lever 241 in its mid-position. Accordingly, displacement of carrier 346, besides moving roller 354, and thus the point of engagement D along the lever, and thus adjusting the transmission ratio thereof by varying distance $BD=y$ (while leaving distance $BC=x$ the same), rotates, by motion of pin 357 (D⁰) parallel to the lever in its mid-position the secondary lever 358 about its fulcrum E⁰, and thereby displaces pin 230 (A⁰), and thus anchorage 218 of the balancing spring, parallel to the centre-line thereof, thus adjusting the deflection l_x of this spring, all this being effected by one outside actuating motion, viz. a rotation of knob 349.

As already explained, with reference to Figs. 6, 7, 8 and 9 this spring lever balancing mechanism varies the degree of irregularity $\delta_{x(x,0)}$ of the governor according to a required function over the range of speed-settings, which function is determined by the shape of the part 259 of the slot in the lever.

Fig. 12 shows an embodiment of a spring lever balancing mechanism in which, for a change of speed-setting, the transmission-ratio of the lever is changed by adjustment of the distance z between the point of action C of the balancing spring on the lever and the fulcrum B of the lever, the distance BD between this fulcrum and the point of action D of the sleeve on the lever remaining the same, while the angle ϕ between the centre-line of the balancing spring and the lever in its mid-position is also changed, together with the deflection l_x of the balancing spring for the lever in its mid-position, such that the degree of irregularity $\delta_{x(x,0)}$ of the governor may remain the same for all speed-settings, or may vary according to a desired function over the range of speed-settings.

The spring-lever balancing mechanism comprises the lever 501, 502, fulcrumed on the shaft 18 mounted in the casing 13, the tension spring 215, the anchorage member 218 for the one end of spring 215, which is immovable during governing at the same speed-setting, the "first" connection means 22 between the other end of spring 215 and the straight lever-part 502, engaging this through roller 23, and the "second" connection means between the straight part 501 of the lever and the extension 343 from the sleeve of some centrifugal mechanism, which is not shown. Anchorage 218 for the one end of the spring 215 is mounted in guides 504 of a carrier-member 503, which is mounted on a shaft 506 in housing 13, and rotatable about that shaft and adapted to be fixed in a desired angular position from outside casing 13 by the provision shown, which is described hereafter. The "first" connection means 22 between the spring 215 and the lever arm 502 is guided so as to be capable of motion only along the centre-line of carrier 503 by means of two rollers 46, mounted on extension 45 from connection means 22, which respectively, engage guides 47 parallel to the centre-line of the carrier 503. The anchorage 218 of the other end of the spring 215 has a pin 230, which engages a curved guide-slot 508 in a member 507 fixed in the casing, anchorage 218 thus being movable

along this guide-slot 507 and in the straight guides 504 of the carrier-member 503, with rotation of this member about its shaft 506. Through these provisions, for a rotation of carrier-member 503 about its shaft 506 to effect a change of speed-setting, which involves a change of angle ϕ , the position of the engagement roller 23 on the lever-arm 502, and thus of point of engagement C is changed, adjusting distance $BC=x$, and by the displacement of both the connection means 22 for the one end of spring 215 and the anchorage 218 for the other end of spring 215 along the centre-line line of action CA⁰ of said spring, the deflection l_x of the balancing spring is also adjusted.

Lever arm 20 fixed on fulcrum axle 18 outside the housing 13 leads to the control-organ of the engine to be governed.

The provision for rotating the carrier 503 for the balancing spring and its guide-means is here shown to comprise forked arm 511 extending from said carrier 503, and engaging the pin 512 set in slide 513, the said slide being held between guides 514 by means of screw 515 mounted in the casing 13. To effect a rotation of carrier 503 for a change of speed-setting, screw 515 is rotatable by means of milled head 516 outside the casing 13, which effects a displacement of slide 513, and thereby rotation of arm 511, with the whole of carrier 503, about its axle 506.

Fig. 13 shows an alternative detail of the construction shown in Fig. 12, in which instead of the straight lever part 502 a curved lever part 516 is provided, the detail being otherwise identical with the corresponding detail of Fig. 12. The curvature of the balancing lever will effect a further variation of the degree of irregularity over the range of speed-setting, and may be used in preference to a designed curvature of the guide-slot 508 if it is desired to keep this to a simple geometrical shape, or for similar reasons.

Since the centre-line of the spring-means is rotated for a change of speed-setting about axle 506 (point G), there is a further geometrical relation derived from Fig. 11, viz.

$$\cot \phi = (x - H \cos Q) / H \sin \phi$$

where Q represents the angle GBC, and H the distance GB, as indicated, both these quantities being constants.

It will be understood that the preceding description is by way of example only, the drawings being diagrammatic, and that many additions, omissions and modifications can be carried out within the scope of the appended claims.

Generally, for any speed responsive device, the spring-lever balancing mechanism of Fig. 12 will be designed in accordance with the Equations (128), (125) and (129), the properties of the speed responsive device for substitution into these equations of $L_{\phi}(x, 0)$ and its differential coefficients with respect to z being known.

It will be understood that the foregoing description of embodiments of the invention is by way of example only, and that many other examples and modifications, omissions and additions are possible without departing from the spirit of the invention.

For clarity's sake, the symbols used throughout the specification and the following claims are collected hereafter and defined as follows:

ω =speed of rotation of governor shaft, or the like;
 K =rate of spring means;
 A^0 =point marking the region of engagement of the spring-anchorage with the support therefor;

C =point marking the region of contact of the first connection (from the spring-means) to the lever;

B =fulcrum of lever;

D =point marking the region of engagement of the second connection means (from the sleeve of the speed responsive device) to the lever;

$x=BC$;

$y=BD$;

Δa =half the travel of the sleeve member of the speed responsive device, extending to either side of its mid-position;

z =distance of the sleeve-member of the speed responsive device from its mid-position;

$\beta=\angle CBA^0$;

$\phi=\angle BCA^0$;

$A^0 C = U_z = U_0 \pm l_x$;

U_0 is the unstrained length of the spring-means

l_x is the deflection of the spring-means from its unstrained length;

$L_{\omega(x, 0)}$ and $S_{\omega(x, 0)}$ are the moments respectively exerted at the fulcrum B of the lever by the speed responsive devise and by the spring-lever balancing mechanism respectively, for static equilibrium between these moments only—i. e. for the “beginning” of static equilibrium—in the mid-position of said sleeve-member ($z=0$), to which corresponds $\omega_{(x, 0)}$ the shaft speed in this state and position, which is denoted the speed-setting.

$\delta_x = \frac{\omega_{(x, \Delta a)} - \omega_{(x, -\Delta a)}}{\omega_{(x, 0)}}$ is the degree of irregularity of the governing mechanism at speed-setting $\omega_{(x, 0)}$, $\omega_{(x, \Delta a)}$ and $\omega_{(x, -\Delta a)}$ being the highest and lowest shaft-speeds for the “beginning” of static equilibrium in the extreme sleeve-positions $+\Delta a$ and $-\Delta a$ respectively.

I claim:

1. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to a control-organ of an apparatus to be governed, and an adjustable spring-lever balancing mechanism for said speed responsive device, which comprises a lever transmission arrangement, a spring-means, an anchorage for said spring-means, a support for said anchorage in all positions of said anchorage, a first connection means engaging both another part of said spring-means and said lever transmission arrangement, a fulcrum for said lever transmission arrangement, a support for said fulcrum, a second connection means engaging both said lever transmission arrangement and said sleeve-member of said speed responsive device, and speed-setting adjustment means comprising a first means for displacing relative to said fixture at least one of three components respectively recited as said first connection means, said fulcrum and said second connection means;

2. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to a control-organ of an apparatus to be governed, and an adjustable spring-lever balancing mechanism for said speed responsive device, which comprises a lever transmission arrangement, a spring-means, an anchorage for said spring-means, a support for said anchorage in all positions of said anchorage, a first connection means engaging both another part of said spring-means and said lever transmission arrangement, a fulcrum for said lever transmission arrangement, a support for said fulcrum, a second connection means engaging both said lever transmission arrangement and said sleeve-member of said speed responsive device, and speed-setting adjustment means comprising a first means for displacing relative to said fixture at least one of three components respectively recited as said first connection means, said fulcrum and said second connection means;

3. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to a control-organ of an apparatus to be governed, and an adjustable spring-lever balancing mechanism for said speed responsive device, which comprises a lever transmission arrangement, a spring-means, an anchorage for said spring-means, a support for said anchorage in all positions of said anchorage, a first connection means engaging both another part of said spring-means and said lever transmission arrangement, a fulcrum for said lever transmission arrangement, a support for said fulcrum, a second connection means engaging both said lever transmission arrangement and said sleeve-member of said speed responsive device, and speed-setting adjustment means comprising a first means for displacing relative to said fixture at least one of three components respectively recited as said first connection means, said fulcrum and said second connection means;

35

displacements of the said components being mutually interdependent, being carried out simultaneously with only one actuating means, and corresponding to one another.

2. A variable speed governing mechanism, which comprises a fixture, a governor shaft rotatably mounted on said fixture, a speed responsive device having a sleeve-member for performing motion responsive to changes of speed of rotation of said governor shaft, means for transmitting motion of said sleeve-member to a control-organ of an apparatus to be governed, and an adjustable spring-lever balancing mechanism for said speed responsive device, which comprises: a lever transmission arrangement, a spring means, an anchorage for said spring means, a support for said anchorage in all positions of said anchorage, a first connection means engaging both another part of said spring means and said lever transmission arrangement, a fulcrum for said lever transmission arrangement, a support for said fulcrum, a second connection means engaging both said lever transmission arrangement and said sleeve-member of said speed responsive device, a means for limiting the travel of said sleeve member, said limiting means comprising a stop, and speed-setting adjustment means comprising a first means for displacing relative to said fixture at least one of four components respectively recited as said first connection means, said fulcrum, said second connection means and said limiting means for the travel of said sleeve-member of said speed-responsive device; a second means for displacing said anchorage of said spring means relative to said support for said anchorage, relative to said fixture, and relative to said first connection means with a change in the distance between the said anchorage and the said first connection means, the said anchorage being immovable relative to said fixture with said adjustment means out of action; and one actuating means for said first and said second displacement means, the said actuating means being out of contact with said lever transmission arrangement; the said speed-setting adjustment means effecting the said displacements of said components to involve a change in the deflection of said spring means at least for the mid-position of said sleeve-member, and the said displacements of the said components being mutually interdependent, being carried out simultaneously with only one actuating means, and corresponding to one another.

3. A variable speed governing mechanism as claimed in claim 2 in which the said displacements of the said components involve a change in the deflection l_x of said spring means at least for the mid-position of said sleeve-member, together with a change of at least another three of the dimensions x , $\angle\phi$, BA^0 , $\angle\beta$, y , and Δa ; the point of engagement A^0 between said spring-anchorage and said support thereof being displaced along a path relative to a system of coordinates having its origin at the fulcrum B and one axis along said lever in the mid-position thereof, the said path being determined relative to said system of coordinates by the dimensions U_x , $\angle\phi$ and x which are obtained for each speed-setting in accordance with the equilibrium-equation

$$L_{\omega(\phi,0)} - S(x,0) = 0 \quad (1)$$

and in accordance with at least the first equa-

36

tion of the series of stability differential equations from the first to the n th order

$$\frac{d}{dz}(L_{\omega(\phi,0)}) - \frac{d}{dz}(S(x,0)) = 0 \quad (25)$$

5 to

$$\frac{d^n}{dz^n}(L_{\omega(\phi,0)}) - \frac{d^n}{dz^n}(S(x,0)) = 0 \quad (36)$$

10 where n is any positive integer excluding unity, where z is the ordinate of the sleeve-position in the second system of coordinates having its origin in the mid-position of said sleeve-member and its Z -axis along the sleeve-travel.

15 4. A variable speed governing mechanism as claimed in claim 2, in which said speed responsive device is a centrifugal mechanism comprising at least one centrifugal body, means for rotating said centrifugal body about said governor shaft, and means for causing motion of said sleeve-member corresponding to radial motion of said centrifugal body in a ratio

$$\frac{dR}{dz} = U$$

25 which is the same for all positions z of said sleeve-member; in which said adjustment means comprises a means for guiding said first connection means between said spring means and said lever along a straight line which is fixed relative to said anchorage, the said straight line being the line of action of said spring means, and in which the said first connection means is movable along said lever, whereby the motion of said first connection means conforms to the relation

$$\frac{dx}{d\beta} = x \cot \phi$$

30 in which the said speed-setting adjustment means effects a change in the deflection l_x of said spring means at least for the mid-position of said sleeve-member together with a change of at least another three of the dimensions x , $\angle\phi$, BA^0 , $\angle\beta$, y and Δa ; the point of engagement A^0 between said spring-anchorage and said support thereof being displaced along a path relative to a system of coordinates having its origin at the fulcrum B and one axis along said lever in the mid-position thereof, and the said path being determined by the dimensions U_x , $\angle\phi$ and x which, together with the above-mentioned dimensions, are obtained in accordance with the equilibrium-equation

$$\omega_{(\phi,0)}^2 \cdot M.R.U_y = k.l_x \cdot x \frac{1}{\sin \phi} \quad (54)$$

35 and in accordance with at least the first equation of the series of stability-equations from the first to the fourth order

$$\frac{x}{l_x} = \frac{x}{U_x - U_0} = \sin \phi \left[y \left(\frac{\delta_x}{\Delta a} - \frac{U}{R} \right) + 2 \cot \phi \right] \quad (144)$$

40 the stability-equation of the second order

$$\frac{\delta_x}{\Delta a} = \frac{3 \cot \phi}{y} \frac{U}{R} \pm \sqrt{\left(\frac{U}{R} \right)^2 + \frac{3 \cot^2 \phi}{y^2} + \frac{2}{y^2}} \quad (155)$$

45 the stability-equation of the 3rd order

$$\frac{\delta_x}{\Delta a} \left[\left(\frac{U}{R} \right)^2 - \frac{3}{\sin^2 \phi \cdot y^2} \right] = \left(\frac{U}{R} \right) \frac{3}{\sin^2 \phi \cdot y^2} + \frac{3 \cot \phi}{y} \left[\left(\frac{U}{R} \right)^2 - \frac{4}{y^2 \sin^2 \phi} \right] \quad (156)$$

the stability-equation of the 4th order

$$\frac{\delta_x}{\Delta a} \left[\left(\frac{U}{R} \right)^3 - \frac{3 \cot \phi}{\sin^2 \phi \cdot y^3} \right] = \frac{3}{y^4 \sin^4 \phi} (3 - \sin^2 \phi) + \frac{3 \cos \phi}{y^3 \sin^3 \phi} \left(\frac{U}{R} \right) + \frac{3 \cot \phi}{y} \left[\left(\frac{U}{R} \right)^3 - \frac{3 \cos \phi}{y^3 \sin^3 \phi} \right] \quad (157)$$

5. A variable speed governing mechanism as claimed in claim 2, in which said speed responsive device is a centrifugal mechanism comprising at least one centrifugal body, means for rotating said centrifugal body about said governor shaft, and means for causing motion of said sleeve-member corresponding to radial motion of said centrifugal body in a ratio

$$\frac{dR}{dz} = U$$

which is the same for all positions z of said sleeve-member; in which said first connection means for said spring-means with said lever has its point of engagement C with said lever immovable relative to said lever, thereby conforming to the relation

$$\frac{dx}{d\beta} = 0$$

and in which the said speed-setting adjustment means effects a change in the deflection l_x of said spring means at least for the mid-position of said sleeve-member, together with a change of at least another three of the dimension x , $\angle \phi$, BA^0 , $\angle \beta$, y and Δa , the point of engagement A^0 between said spring-anchorage and said support thereof being displaced along a path relative to a system of coordinates having its origin at the fulcrum B and one axis along said lever in the mid-position thereof, and the said path being determined by the dimensions U_x , $\angle \phi$ and x which are obtained in accordance with the equilibrium-equation

$$\omega^2 (x, 0) \cdot M.R.v.y = k.l_x.x \cdot \sin \phi \quad (141 \text{ A})$$

and in accordance with the stability-equation of the first order

$$\frac{x}{l_x} = \sin \phi \left[\left(\frac{\delta_x}{\Delta a} + \frac{U}{R} \right) y + \cot \phi - \frac{x \cot \phi \cos \phi}{U_0 \pm l_x} \right] \quad (142 \text{ A})$$

6. A variable speed governing mechanism which comprises a fixture, a governor shaft rotatably mounted on said fixture, a speed responsive device having a sleeve-member for performing motion responsive to changes in speed of rotation of said governor-shaft, means for transmitting motion of said sleeve-member to a control-organ of an engine to be governed, and an adjustable spring-lever balancing mechanism for said speed responsive device which comprises a lever, a spring-means, an anchorage for said spring-means, a support for said anchorage in all positions of said anchorage, a first connection means engaging both another part of said spring-means and said lever, a fulcrum for said lever, a support for said fulcrum, a second connection means engaging both said sleeve of said speed responsive device and said lever, and speed-setting adjustment means comprising a means for guiding said first connection means along a straight line which is fixed relative to said anchorage, said straight line being hereafter referred to as the line of action of said spring means, a first guide-surface for said anchorage of said spring-means, said first guide-surface

having at each point thereof an inclination to said line of action of said spring-means, said first guide-surface being mounted on said fixture, means for holding said anchorage immovable relative to said first guide-surface and relative to said fixture with said speed-setting adjustment means out of action, and means for displacing said anchorage along said first guide-surface and for maintaining said line of action of said spring-means parallel to itself in all positions of said anchorage, and only one actuating means for said displacement means, said actuating means being out of contact with said lever; whereby speed-setting adjustment involves a displacement of said first-connection means along said lever and relative to said fixture and a displacement of said spring-anchorage along said inclined first guide-surface therefore, with a change in the deflection of said spring-means at least in the mid-position of said lever.

7. A variable speed governing mechanism comprising an adjustable spring-lever balancing mechanism as claimed in claim 6, in which said speed-setting adjustment means comprises: said guide-means for said first connection means, said first guide-surface for said anchorage of said spring-means, which guide-surface has at each point an inclination to said line of action of said spring-means, a carrier for said anchorage and for said means for guiding said first connection along the line of action of said spring-means, a second guide-surface in said carrier for adjustably mounting said anchorage of said spring-means, said second guide-surface extending parallel to the said line of action of said spring-means, a straight third guide-surface on said fixture for adjustably mounting said carrier, said third guide-surface having an inclination to the said line of action of said spring-means, means for displacing said carrier along said third guide-surface, and one actuating means for said displacement means for said carrier, the said actuating means being out of contact with said lever; the said speed-setting adjustment means effecting a displacement of said carrier along said straight third guide-surface with said carrier remaining parallel to itself, thereby moving the line of action of said spring-means parallel to itself, which involves a displacement of the said first connection means between said spring means and the said lever along said lever and relative to said fixture, and which involves a displacement of said anchorage along said first guide-surface inclines to said line of action of said spring-means, and thus also a displacement along said second guide-surface in said carrier, which effects a change in the deflection of said spring-means at least in the mid-position of said lever.

8. A variable speed governing mechanism comprising an adjustable spring-lever balancing mechanism as claimed in claim 6, which further comprises means for adjusting the position of said first guide-surface relative to said fixture.

9. A variable speed governing mechanism comprising an adjustable spring-lever balancing mechanism as claimed in claim 6, in which said lever is, at least in part, curved.

10. A variable speed governing mechanism comprising an adjustable spring-lever mechanism as claimed in claim 6, which comprises means for angularly adjusting the position relative to said fixture of the said guide-means for said first connection means, which determines the line of action of said spring-means.

11. A variable speed governing mechanism comprising an adjustable spring-lever balancing mechanism as claimed in claim 1, in which said speed-setting adjustment means comprises means for adjusting the magnitude of the travel of the sleeve-member of said speed responsive device, the said means comprising: a transmission member mounted in said fixture and connecting to the control-organ of an apparatus to be governed, a third connection means for engaging said lever movably therealong and for engaging said transmission member movably relative thereto in the direction parallel to the mid-position of said lever, a carrier for said third connection means, a guide-means in said carrier for permitting motion of said third connection means relative to said carrier only along a straight line fixed relatively to said carrier, the said straight line being the centre-line of said carrier, and being inclined to the said lever in the mid-position thereof, stops for limiting the motion of said third connection means relative to said carrier, means for holding said carrier immovable relative to said fixture with said adjustment means being out of action, a third means for displacing said carrier for said third connection means with the centre-line of said carrier remaining parallel to itself, the said speed setting adjustment means comprising one actuating means for said first, said second and said third displacement means for producing simultaneous and interdependent displacements of said components acted upon by said displacement means, the said actuating means being out of contact with said lever.

12. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to the control-organ of an apparatus to be governed and an adjustable spring-lever balancing mechanism which comprises a lever, a spring means, an anchorage for said spring-means, a first connection engaging both another part of said spring-means and said lever, a fulcrum for said lever, a support for said fulcrum, a second connection engaging both said lever and said sleeve-member of said speed responsive device, and speed-setting adjustment means comprising a carrier for said support of said fulcrum, a secondary guide-surface on said fixture for adjustably mounting said anchorage of said spring-means, said anchorage being immovable relative to said fixture with said adjustment means out of action, the said secondary guide-surface being inclined to said lever in the mid-position thereof, a transmission means between said carrier for said support of said fulcrum and said anchorage for said spring-means, a first means for displacing said carrier relative to said fixture, and one actuating means for said displacement means, the said actuating means being out of contact with said lever, the said speed-setting adjustment means effecting in mutual interdependence, simultaneously with only one actuating motion, and in correspondence with one another a displacement of said fulcrum of said lever relative to said fixture and, through said transmission means, a displacement along said secondary guide surface, parallel to said line of action of said spring-means, of said anchorage for said spring-means, which effects a change in the de-

flection of said spring-means at least in the mid-position of said lever.

13. A variable speed governing mechanism comprising an adjustable spring-lever balancing mechanism as claimed in claim 12, in which said lever is straight, and in which said speed-setting adjustment means further comprises: a third guide-surface on said fixture for adjustably mounting said carrier, said third guide-surface extending parallel to the mid-position of said lever; and in which said transmission means comprises an extension from said carrier having a curved transmission-surface for engaging said anchorage of said spring-means, a means for displacing said fulcrum-carrier parallel to said lever in the mid-position thereof, and one actuating means for said displacement means, the said actuating means being out of contact with said lever.

14. A variable speed governing mechanism comprising an adjustable spring-lever mechanism as claimed in claim 12, in which said adjustment means comprises: a third guide-surface on said fixture for adjustably mounting said carrier, said third guide-surface extending parallel to said lever in the mid-position thereof; and in which said transmission means comprises a secondary lever fulcrumed on said fixture and having a transmission surface for engaging said fulcrum-carrier and said anchorage for said spring-means; means for displacing said carrier relative to said fixture and parallel to said lever in the mid-position thereof, and one actuating means for said displacement means for said carrier, the said actuating means being out of contact with the said speed-setting adjustment means.

15. A variable speed governing mechanism comprising an adjustable spring-lever balancing mechanism as claimed in claim 12, and which further comprises means for adjusting the travel of said sleeve of said speed responsive device, said means comprising a second transmission-member mounted in said fixture and connecting to said control-organ of an apparatus to be governed, a third connection means between said transmission member and said lever, and stops for limiting the travel of said transmission member in the direction parallel to the travel of said sleeve-member of said speed responsive device, the said third connection means engaging said lever on that side of the fulcrum, which is remote from the region of engagement of said first connection means from said spring-means with said lever.

16. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to the control-organ of an apparatus to be governed, and an adjustable spring-lever balancing mechanism which comprises a lever, a spring-means, an anchorage for said spring-means, a first connection means engaging both said spring-means and said lever, a fulcrum for said lever, a support for said fulcrum, a second connection means for engaging said lever movably therealong and for engaging said sleeve-member of said speed responsive device movably relative thereto in the direction parallel to the said lever in the mid-position thereof, and speed-setting adjustment means

which comprises a carrier for said second connection means, a guide-means in said carrier for permitting motion of said second connection means relative to said carrier only parallel to the travel of said sleeve-member of said speed responsive device, a third guide-surface on said fixture, said third guide-surface extending substantially parallel to said lever in the mid-position thereof, for adjustably mounting said carrier on said fixture, a second guide-surface on said fixture, the said guide-surface being inclined to said lever in the mid-position thereof, for adjustably mounting said anchorage for said spring means, the said anchorage being immovable relative to said fixture with said adjustment means out of action; a transmission means between said carrier and said spring-anchorage, a means for displacing said carrier relative to said fixture, substantially parallel to said lever, and an adjustment means for said displacement means for said carrier, said adjustment means being out of contact with said lever; the said speed-setting adjustment means effecting a displacement of said carrier parallel to said lever and thereby a displacement relative to said fixture of said second connection means between said lever and said sleeve-member of said speed responsive device and, in dependence thereon, simultaneously therewith and in correspondence thereto, a displacement of said spring-anchorage along said second guide-surface in said fixture, which involves a change in the deflection of said spring-means at least for the mid-position of said lever.

17. A variable speed governing mechanism which comprises a fixture, a governor shaft rotatably mounted on said fixture, a speed responsive device having a sleeve-member for performing motion responsive to changes of speed of rotation of said governor shaft, means for transmitting motion of said sleeve-member to the control-organ of an apparatus to be governed and an adjustable spring-lever balancing mechanism for said speed responsive device, which comprises; a lever, a spring means, an anchorage for said spring-means, a first connection means engaging both another part of said spring means and said lever, a fulcrum for said lever, a support for said fulcrum, a second connection means engaging both said lever and said sleeve-member of said speed responsive device, and a speed-setting adjustment means comprising a first guide-surface mounted in said fixture for engaging said anchorage of said spring means, a carrier for said anchorage, means mounted on said carrier for guiding said first connection means along a straight line fixed relative to said carrier, the said straight line forming the line of action of said spring means, a secondary guide-surface in said carrier for adjustably mounting said anchorage, said secondary guide-surface extending substantially parallel to said line of action of said spring means, an axle in said fixture for mounting said carrier, means for holding said carrier and thereby said anchorage immovable relative to said fixture with said adjustment means out of action, means for effecting a rotational displacement of said carrier about said axle and one actuating means for said displacement means; the said adjustment means effecting in mutual interdependence, simultaneously with only one actuating motion, and in corresponding with one another, a displacement of said first connection means between said spring means and said lever along the said lever, and

a displacement of said spring-anchorage along said first guide-surface, which involves a displacement of said spring-anchorage along said second guide-surface and a change in the deflection of said spring-means at least for the mid-position of said lever.

18. A variable speed governing mechanism as claimed in claim 2, in which said adjustment means comprises a means for guiding said first connection means between said spring means and said lever along a straight line which is fixed relative to said anchorage, the said straight line being the line of action of said spring-means, and in which said first connection means is movable along said lever, whereby the motion of said first connection means conforms to the relation

$$\frac{dx}{d\beta} = x \cot \phi$$

20 in which the said speed-setting adjustment means displaces the point of engagement A^0 between said spring-anchorage and said support thereof along a path relative to a system of coordinates having its origin at the fulcrum B and one axis along said lever in the mid-position thereof, and the said path being determined by the dimensions U_x , $\angle \phi$ and x which, together with the dimensions y and Δa , satisfy the equilibrium-equation

$$L_{\omega(x,0)} = k \cdot l_x \cdot x \frac{1}{\sin \phi} = 0 \quad (129)$$

the stability-equation of the first order

$$35 \quad \frac{x}{U_x - U_0} = \frac{x}{l_x} = \sin \phi \left[\frac{1}{L_{\omega(x,0)}} \left(\frac{dL_{\omega(x,0)}}{dz} \right) y - 2 \cot \phi \right] \quad (128)$$

and the stability-equation of the second order

$$40 \quad \frac{1}{L_{\omega(x,0)}} \frac{d^2 L_{\omega(x,0)}}{dz^2} = \frac{1}{y^2 \sin^2 \phi} \left[\left(\frac{x}{l_x} \right) 6 \cos \phi + 4 \cos^2 \phi + 2 \right] \quad (125)$$

in which the derivatives of $L_{\omega(x,0)}$ contain the degree of irregularity δ_x and the properties of the speed responsive device.

19. A variable speed governing mechanism as claimed in claim 2, in which said first connection means between said spring-means and said lever conforms to the relation

$$50 \quad \frac{dx}{d\beta} = 0$$

by engaging said lever immovably therealong; in which said adjustment means displaces the point of engagement A^0 between said spring-anchorage and said support thereof being displaced along a path relative to a system of coordinates having its origin at the fulcrum B and one axis along said lever in the mid-position thereof, and the said path being determined by the dimensions U_x , $\angle \phi$ and x which, together with the dimensions y and Δa , satisfy the equilibrium-equation

$$L_{\omega(x,0)} - k \cdot l_x \cdot x \cdot \sin \phi = 0 \quad (141)$$

65 and at least the stability-equation of the first order

$$60 \quad \frac{x}{l_x} = \sin \phi \left[\frac{1}{L_{\omega(x,0)}} \left(\frac{dL_{\omega(x,0)}}{dz} \right) y + \cot \phi - \frac{x \cot \phi \cos \phi}{U_0 \pm l_x} \right] \quad (142)$$

70 in which the derivative of $L_{\omega(x,0)}$ contains the degree of irregularity δ_x and the properties of the speed responsive device.

75 20. A variable speed governing mechanism

comprising an adjustable spring-lever balancing mechanism as claimed in claim 12, in which said second connection between said lever on the one hand and said sleeve-member of said speed responsive device on the other hand comprises an extension from said one part, an engagement surface, arranged substantially normally to the travel of said sleeve-member, on said other part, the said extension engaging said engagement surface movably therealong, and elastic means engaging said extension and said part it engages for permitting elastic displacement of said extension relative to the said engagement surface on the said part.

MEYER FRENKEL.
